METHOD OF AND APPARATUS FOR
PACKAGING ARTICLESCharles H. Petskeyes, Davenport, Iowa, assignor
to Micro-Westco, Inc., Bettendorf, Iowa, a cor-
poration of Delaware

Application April 23, 1938, Serial No. 203,852

92 Claims. (Cl. 93—2)

This invention relates to machines for packaging articles and more particularly to a method and machine for packaging relatively soft and compressible articles such as loaves of bread, whether sliced or unsliced.

The invention contemplates the general improvement and simplification of packaging machines and aims to present a commercially desirable wrapper which, in addition to being qualified to handle a multiplicity of sizes and shapes of baked goods such as are ordinarily produced by large bakeries, is simple to operate and adjust, and will not be injured by inadvertent operation with the parts in disadjustment.

One object of the invention is to provide a wrapping machine having means for receiving and individually measuring each article and for feeding a portion of wrapping material thereto from the end of a continuous web in accordance with the size of each measured article.

Another object is to provide a wrapping machine in which wrapping material is fed and carried upwardly and positioned in the path of an article advancing to the wrapping mechanism whereby the leading end of the wrapper may be carried over the top and down the rear side of the article.

Another object is to provide a machine of this character having means to alter and regulate by means of simple adjustments the amount of overlap of the wrapping material and the tightness of the wrapper about the wrapped article, and more specifically to provide such a machine in which these adjustments may be made during continuous operation of the wrapping mechanism.

A further object is to provide an improved machine of this character, simple and inexpensive to manufacture and operate, which accommodates different sized articles with a minimum of manual adjustment and which is smooth and quiet in operation and wraps articles by means of uniform and regular folds.

Other objects and advantages will become apparent as the description of the invention proceeds. This description is made in connection with the accompanying drawings in which like parts are identified by the same numerals of reference throughout the several views. Although the machine illustrated and described is primarily intended for wrapping loaves of bread, the features of the invention which are embodied in the particular construction and combination of parts are applicable and advantageous in machines for wrapping other articles.

In the drawings,

Fig. 1 is a plan view with parts removed of a wrapping machine-slicing machine combination embodying the present invention;

Fig. 2 is a side elevational view of the combination shown in Fig. 1;

Fig. 3 is a side elevational view showing the wrapping machine of the combination illustrated in Figs. 1 and 2, taken from the operator's side thereof;

Fig. 4 is a side elevational view of the wrapping machine shown in the preceding figures, taken on the opposite side from the illustration of Fig. 3;

Fig. 5 is a longitudinal sectional view with parts removed and with parts broken away through the central portion of the wrapping machine illustrated in the preceding figures, being enlarged with respect thereto, and showing the article carrier in its uppermost position at the outfeed station;

Fig. 6 is a fragmentary detail view in section taken on the line 6—6 of Fig. 16 showing the wrapping material severing means to advantage;

Fig. 7 is a sectional view similar to Fig. 5 in which the article carrier is shown in its lowermost position at the infeed station;

Fig. 8 is a fragmentary detail partially in section showing the resiliently mounted roller wheel for yieldingly gripping the wrapping material as the latter is engaged by an article moving onto the carrier at the infeed station;

Fig. 9 is a vertical sectional view with parts removed and with parts broken away, taken longitudinally of the wrapping machine illustrated in the preceding figures, and showing the infeed and discharge or outfeed stations to advantage;

Fig. 10 is a fragmentary detail partially in section taken substantially on the line 10—10 of Fig. 9;

Fig. 11 is a fragmentary detail view in section taken substantially on the line 11—11 of Fig. 9;

Fig. 12 is a fragmentary detail view taken substantially on the line 12—12 of Fig. 9;

Fig. 13 is a fragmentary plan view of a portion of the wrapping machine illustrated in the preceding figures with parts removed and enlarged with respect thereto to show the folding and heat sealing channel and discharge or outfeed conveyor of the wrapping machine;

Fig. 14 is a fragmentary detail in section taken substantially on the line 14—14 of Fig. 13;

Fig. 15 is a fragmentary detail in section taken substantially on the line 15—15 of Fig. 13;

Fig. 16 is a vertical transverse sectional view with parts removed and with parts broken away

taken substantially on the line 16—16 of Fig. 3;

Fig. 17 is a fragmentary detail sectional view taken substantially on the line 17—17 of Fig. 16;

Fig. 18 is a plan view with parts removed and with parts broken away showing the arrangement of the mechanism feeding the wrapping material;

Fig. 19 is an elevational view partly in section and with parts removed showing the mechanism for controlling the length of wrapping material fed for each article in accordance with the size of such article, and taken substantially on the line 19—19 of Fig. 18;

Fig. 20 is a fragmentary detail view in section showing the clutch mechanism for actuating the wrapping material feed rolls and enlarged from the similar view of these parts appearing in Fig. 18;

Fig. 21 is a fragmentary detail partly in section and with parts broken away taken substantially on the line 21—21 of Fig. 3;

Fig. 22 is a fragmentary plan view taken sectionally through the wrapping machine illustrated in the preceding figures and with parts removed, showing the article carrier positioned at the infeed station;

Fig. 23 is a fragmentary detail view taken substantially on the line 23—23 of Fig. 19, showing one feature of the mechanism for timing the start of the wrapping material feed;

Fig. 24 is a fragmentary detail plan view of the feature illustrated in Fig. 23;

Fig. 25 is a fragmentary side elevational view with parts removed and with parts broken away showing the clutch mechanism associated with the wrapping material feed rolls;

Fig. 26 is a diagrammatic side elevational view illustrating the manner in which wrapping material is proportioned in size according to the relative widths of articles being wrapped;

Fig. 27 is a diagrammatic view similar to that of Fig. 26 illustrating the manner in which wrapping material is proportioned in accordance with the heights of articles being fed to the wrapping mechanism;

Fig. 28 is a horizontal sectional view with parts removed taken substantially on the line 28—28 of Fig. 3, to show the driving mechanism;

Fig. 29 is a sectional detail view with parts broken away and with parts removed taken substantially on the line 29—29 of Fig. 28 and illustrating the main clutch of the wrapping machine;

Fig. 30 is a vertical sectional detail view taken substantially on the line 30—30 of Fig. 29;

Fig. 31 is a detail plan view with parts removed and with parts broken away illustrating the mechanism for holding an article down as the latter moves to the outfeed or discharge station of the wrapping machine and is advanced from the carrier to the folding and sealing channel, and the means for moving an article from the carrier into the channel;

Fig. 32 is a vertical detail sectional view taken substantially on the line 32—32 in Fig. 31;

Fig. 33 is a horizontal sectional view taken substantially on the line 33—33 of Fig. 32;

Fig. 34 is a diagrammatic elevational view of the article ram or push-off member shown in the previous figures illustrating how it may be removed from its support;

Fig. 35 is a fragmentary detail plan view, with parts removed, showing the carrier at the outfeed station of the wrapping machine and illustrating a modified construction;

Fig. 36 is a fragmentary side elevational view corresponding to the plan view of Fig. 35;

Fig. 37 is a fragmentary detail side elevational view showing the folding members at the outfeed station of the wrapping machine and an article being removed to the outfeed station by the carrier;

Fig. 38 is a fragmentary vertical sectional view taken substantially on the line 38—38 of Fig. 37;

Fig. 39 is a fragmentary detail view in perspective and with parts broken away of an article being moved to the outfeed station of the wrapping machine by the carrier substantially at the moment the top end prefolders are engaged by the carrier;

Fig. 40 is a fragmentary vertical detail sectional view corresponding to Fig. 38, showing the relative position of the parts substantially at the moment the carrier reaches the outfeed station;

Fig. 41 is a fragmentary sectional view taken substantially on the line 41—41 of Fig. 37 and showing the approximate appearance of an article being advanced through the folding and heat sealing channel at this point;

Figs. 42 and 43 are views similar to that of Fig. 41 taken substantially on the lines 42—42 and 43—43, respectively, of Fig. 37;

Figs. 44 through 49 are diagrammatic vertical sectional views illustrating relationships between the wrapping material feeding and cutting mechanism and the carrier and gripper bars and other parts of the wrapping machine;

Fig. 50 is a diagrammatic plan view corresponding to Fig. 49;

Figs. 51 through 54 are diagrammatic vertical sectional views similar to Figs. 44 through 49, illustrating successive stages in the wrapping of an article;

Fig. 55 is a diagrammatic rear elevational view illustrating the manner in which the end prefolders are moved out of the way of the top end folders as the carrier advances an article to the outfeed station;

Figs. 56, and 58 through 62 are diagrammatic vertical sectional views illustrating successive stages in the wrapping of an article, these views being successive to Figs. 48 through 54 and showing the movement of an article through the folding and heat sealing channel;

Fig. 57 is an enlarged fragmentary detail view in section showing the rollers for tensioning wrapping material about an article; and

Fig. 63 is a diagrammatic elevational view illustrating the mechanism for actuating the carrier of the wrapping machine.

The general manner of operation of the slicing machine-wrapping combination which embodies the various features of the present invention involves the feeding of articles such as loaves of bread through a slicing machine having vertically reciprocable knives and onto the infeed conveyor of the wrapping machine. This conveyor and related parts are given numerals in the one hundreds. It moves continuously and carries the articles individually onto a vertically reciprocable elevator or carrier. In the movement of the articles to the carrier they are measured by a size indicator which controls the wrapping material feeding mechanism which is operated in timed relationship with respect to the infeed conveyor so that a sheet of wrapping material of the proper size is vertically positioned in the path of an article moving toward the elevator or carrier. The related parts of the feeding mechanism are indicated by numerals in the two hun-

dreds, wrapping material positioning mechanism is numbered in the three hundreds, and the article measuring means is numbered in the four hundreds.

As the article moves onto the carrier, numbered in the five hundreds, the leading or first side of the article engages the wrapping material which has previously been severed from the end of a continuous web by a cutting means, numbered in the six hundreds. The wrapping material is draped over the top of the article and the last portion of the wrapping material to be advanced by the feeding mechanism is tucked underneath the leading edge of the article and held between the article and platform of the carrier. Upon movement of the carrier to the discharge or out-feed station, the wrapping material is draped down the rear or second side of the article and a smoothing member strokes over the top and down the side of the article to complete the movement of the article onto the carrier and to smooth the wrapper against the article. Approaching the outfeed station, top end folds are performed on the portions of wrapping material extending over the ends of the article, and at the upper limit of movement of the carrier, the article is pushed therefrom into a folding and sealing channel. The parts of the wrapping machine associated with the wrapping operations during movement of the carrier from the infeed to the outfeed station and into the folding and sealing channel are indicated by numerals in the seven hundreds. The folding and sealing channel and outfeed conveyor associated therewith have parts numbered in the eight hundreds. Numerals in the nine hundreds designate the parts concerned with the adjustment of the conveyors to accommodate articles having different lengths and the parts of the combined slicing and wrapping mechanism which are not otherwise numbered as indicated above are given numerals under 100.

It is to be understood that all of the parts and groups of parts are related to one another and classifications and grouping other than that outlined above may be made. The wrapping machine functions as a single unit of coordinated movements and mechanisms, all of which contribute to the final result and the consideration of several parts together as a group is for purposes of explanation and description in order to facilitate the location of the several parts in the drawings and their place in the specification.

The paths of the articles through the slicing machine, infeed conveyor, wrapping mechanism, and discharge conveyor are substantially in a common vertical plane, and during their movement the articles are at all times supported from underneath so that there is a minimum of squeezing and deformation thereof. Furthermore, the discharge of the completed packages is directly above the station in which unsliced articles are fed to the slicing machine so that operation of the combination by a single attendant may be advantageously accomplished.

Referring to Figs. 1 and 2 the wrapping machine 1 is indicated at the left of the illustrations and the slicing machine 2 at the right. The driving mechanism for the reciprocable blades of the slicing machine is contained within the side frames 3 thereof and powered by an electric motor. The remainder of the mechanism, including all the conveyors for both the wrapping machine and slicing machine, together with the wrapping mechanism and wrapping material

feeding mechanism, is driven in synchronous timed relation by means of a motor 4 of the wrapping machine.

The wrapping machine comprises a pair of side frames 5 and 6 between which extend a plurality of cross members. Cross member 7 (Fig. 3) is positioned at the top of the machine at the rear or left end thereof as viewed in Figs. 1, 2 and 3. Cross member 8 is positioned between the side frames at the lower portion thereof and across the rear end. Cross member 9 is positioned at the bottom and front or right hand end of the machine as viewed in Figs. 1, 2 and 3. Cross member 10 is positioned in the central portion of the wrapping machine and cross members 11 and 12 extend between the side frames at the top and front end thereof to carry the members of the folding and heat sealing channel.

Articles are deposited on the infeed conveyor of the slicing machine, which operates in timed relation with the wrapping mechanism, and are fed to and through the slicing machine blades (not shown). Emerging from the slicing machine over its discharge plate the articles are individually engaged by flights of a conveyor for carrying the articles to the wrapping mechanism.

Article infeed mechanism

The conveyor which extends from the discharge plate of the slicing machine 2 for carrying articles from the latter to the wrapping machine may also be used for the infeed conveyor of the wrapping machine when unsliced articles are to be wrapped. It comprises a pair of spaced parallel supporting members 100 and 101 which may be suitably formed of steel channels disposed in opposed relation with vertical web portions and flanges disposed inwardly so that the channels of the members open toward one another (Figs. 9 and 19). The wrapping machine end of the conveyor is carried by a transverse rod 102 secured by nuts in reinforced elongated slots 103 formed in the side frames 5 and 6 to provide vertical adjustment of this end of the conveyor. The extremities of the supporting members 100 and 101 extend a substantial distance inwardly of the rod 102 (Fig. 9), and are provided with fittings 104 (Figs. 9 and 22), which serve as journals for a transverse driven shaft 105. The ends of the shaft 105 carry conveyor chain sprockets 106 and the shaft carrying portions or journals 107 of the fittings 104 (Fig. 22) are formed inwardly of the members 100 and 101 so that the sprockets 106 are positioned substantially in alignment with the members 100 and 101. Conveyor side chains 108 are carried in spaced parallel relation by the sprockets 106 and a similar pair of sprockets (not shown) carried by a transverse shaft at the opposite end of the conveyor supporting members 100 and 101 and supported at 109 (Fig. 2) in the side frames 3 of the slicing machine 2.

Extending between and carried by the uppermost flanges of the supporting members 100 and 101 is an article supporting apron 110. The side marginal portions of the apron are disposed upwardly to form rails 111 (Fig. 19) parallel with the supporting members 100 and 101. The end of the apron 110 at the wrapping machine end of the infeed conveyor is referred to as the infeed station of the wrapping machine since it is here that articles first engage wrapping material and are then moved onto the reciprocable carrier. The portion of the apron 110 which

forms the infeed station is above the shaft 105 and marginal portions are removed (Figs. 18 and 22) to provide recesses 112 which accommodate the conveyor belt sprockets 106.

The endless conveyor belts or chains 108 carry between them at uniformly spaced intervals flights 113 which include a main pusher or rod 114 and auxiliary pushers 115 (Fig. 19). The main pusher bar is journaled in extensions of special link elements 116 of the chains 108 and rotatably carried in slightly spaced relation with respect to the apron 110 of the conveyor. As each flight is carried around the sprockets at the slicing machine end of the conveyor the auxiliary pushers trail the main pusher so that the latter may pass closely adjacent the underside of the discharge plate of the slicing machine and above the apron 110. The auxiliary pushers remain in this trailing position until the flight has moved away from the discharge plate of the slicing machine; they are then elevated to their upright pushing position. Secured to one extremity of each of the main pushers 114 is a cam 118 which rides upon a track 119 (Fig. 4) and in cooperation therewith serves to elevate the auxiliary pusher 115 and maintain them in an upright position while they are serving to advance an article. The main pusher 114 first engages the article discharged from the slicing machine and advances such article a short distance toward the infeed station of the wrapping machine before the auxiliary pushers 115 are rotated by engagement of the cam with the track into article-advancing position to assist in pushing. This elevation of the auxiliary pushers by rotation of the main pusher 114 on the journal link 116 serves to thrust forward an article that may be riding on the top of the main pusher, so that in any event the article is positively moved along the apron 110 in advance of the flight. The auxiliary pushers 115 may be formed of metal strips individually secured to the main pushers 114 in spaced relation with respect to one another with article contacting faces lying substantially in a plane so that all of the elements may engage an article substantially simultaneously. The pushers 115 are positioned along the main pusher 114 at substantially uniform intervals and separated from one another by spaces 120 so that the feelers or gauges of a loaf measuring mechanism, to be hereinafter described, can pass therethrough and extend to a position very close to the conveyor apron 110. The auxiliary pushers 115 remain in engagement with the article until the latter is received by the carrier of the wrapping mechanism. In this manner the auxiliary pushers 115 which extend for a substantial distance above the apron 110 provide a firm support for the rear side of the articles being advanced into the wrapping mechanism. This is of considerable advantage since in moving the articles onto the carrier, preliminary wrapping operations are performed and it is desirable that the articles be well supported along their rear sides to prevent deformation or injury thereof.

The sprockets 106 secured on the shaft 105 rotate in synchronous timed relation and maintain the flights in proper transverse position across the conveyor apron. The shaft 105 extends beyond one of the sprockets 106 toward the side frame 5, and has secured thereto a sprocket 122 (Fig. 22) around which runs a driving chain 123 driven by sprocket 126 secured to and carried by driving shaft 13 (Figs. 9 and 28),

which is driven at substantially uniform rotational velocity and in synchronization with the remainder of the mechanism as will be herein-after described. The chain 123 passes over idling sprocket 128 carried loosely on an intermediate shaft of the machine and idling sprocket 124 carried by supporting member 100 to direct the chain through a circuitous path in order to avoid interference with other parts of the wrapping machine.

Loading tray

Extending between the machines on the operator's side of the packaging combination is a loading tray having an article supporting apron 130 (Fig. 1). This tray is carried by the supporting member 101 and slopes downwardly away from the upper edge of the rail 111 at the side of the apron 110. The edge of the loading tray adjacent the article supporting apron 110 of the conveyor is thus slightly above the level thereof and may even be slightly above the level of the top of the rail 111 so that articles may be readily slid from the apron 130 of the loading tray onto the apron 110 of the infeed conveyor without being lifted over any intervening obstruction. The width of the apron 130 is less than the average length of articles to be packaged by the machine combination and the lower edge thereof terminates in an upstanding stop or curb 131, the top edge 132 (Fig. 2) of which is substantially level with the edge of the apron 130 positioned adjacent the conveyor apron 110. Along the top edge of the stop 131 is a substantially flat or horizontal shelf 133 parallel to, and in spaced relationship with, the edge of the apron 130 which is disposed adjacent the infeed conveyor, and in like relation with the rail 111 of the indeed conveyor. The shelf 133 is substantially level with the top of the rail 111 and articles B of considerable length may be disposed so as to have one end extending over and supported by rail 111 and another or opposite end extending over and supported by the shelf 133.

Articles C of average size may be positioned as indicated in Fig. 1 with one end abutting against the stop 131 of the loading tray. These articles may be readily projected onto the apron 110 of the infeed conveyor in advance of a flight by a flick of an operator's hand on account of there being no obstruction between the tray and the conveyor apron. However, the slope of the tray retains the articles thereon so that they do not accidentally slide onto the conveyor apron. In the event that the operator wishes to support an article on the loading tray without requiring that it be in position to be readily flicked onto the infeed conveyor, it may be placed as indicated at D, in the deeper portion or trough of the loading tray so that it is not likely to become dislodged and will not be inadvertently moved into the path of flights traveling over the conveyor apron.

Wrapping material supply feed

The wrapping material is supplied in one or more continuous sheets or strips which are in the form of rolls (indicated at R1, R2 and R3, Figs. 2 and 3). The operation of the machine is substantially the same whether a single roll such as the roll R1 is employed to feed a single thickness of wrapping material, or whether a plurality of rolls to feed several thicknesses such as an inner and outer wrap and a liner or band. In

the usual arrangement having a multiplicity of sheets, wrapping material to form the outside wrapper is positioned at R1, that forming the inner wrap at R2, and the band or liner at R3. The rolls R1 and R2 are carried on cone shaped bushings or collets 201 which frictionally engage the central axial aperture through the roll and are in turn frictionally engaged and rotatably supported in cone shaped sockets 202 formed in brackets 203. The brackets 203 are each supported at two corners, the lower corner having a sleeve slidably carried on a smooth rod 204 extending between the side frames 5 and 6. The upper corner of each bracket has an elongated, internally threaded sleeve 205 which is carried by a rotatable shaft 206 journalled in the side frames of the wrapping machine above the corresponding smooth shaft 204. The shafts 206 have oppositely threaded ends which engage the threads of the elongated sleeves 205 of the brackets. Upon rotation of the shafts 206, by means of hand wheels 207, the wrapping material roll supporting brackets 203 may be moved towards and away from each other. By this manipulation the cone shaped journals or sockets 202 can grip the collets or cones 201 with variable pressure to increase or decrease the force or energy required to rotate the rolls of wrapping material.

To facilitate the positioning of a new roll of wrapping material between the brackets 203 the collets 201 are centrally apertured to receive a bar 208 (Figs. 3 and 4). An upwardly directed reinforced slot 209 is formed in each of the cone shaped journals or sockets 202. Accordingly, when positioning a new roll of wrapping material in the machine the brackets 203 are moved apart by means of the hand wheel 207 and the new roll having the collets 201 inserted in each end of its axial aperture is elevated into position by means of the rod or bar 208 which extends through axial apertures in the collets 201. End portions of the rod are received in the slots 209 and upon drawing the brackets 203 together the cone sockets 202 frictionally engage the cone shaped ends of the collets 201 to thereby support the roll of wrapping material independently of the bar 208. Since the threads on the shafts 206 are arranged to move the brackets 203 equal increments in opposite directions, each roll of wrapping material is automatically centered with respect to the wrapping mechanism.

The liner or banding roll R3 is carried by a shaft 211 which has one end adjustably carried in a bracket member 212 depending from cross member 8 of the wrapping machine. The roll R3 is retained on the shaft 211 by a disk 213. By means of a hand wheel 214 the grip of journal 215 on the shaft 211 may be released so that the shaft 211 may be moved into or out of the journal in accommodating band rolls R3 of various widths.

The free end of the wrapping material from each of the rolls R2 and R3 is led underneath a booster roll 217 (Figs. 5 and 44) which is journalled between the side frames 5 and 6 at 218 and 219 respectively, immediately below the smooth shaft 204 which supports the bracket 203 of the top wrapping material roll R1. The shaft on which the booster roll 217 is journalled extends beyond the side frame 5 and carries a gear 220 which meshes with a gear (not shown) carried on and driven by a stub shaft upon which is secured sprocket 221 (Fig. 4). This sprocket is driven by a chain or belt 222 from sprocket 75

223 which is secured on driving shaft 15. Near the sprocket 221 the chain 222 is carried over an idling sprocket 224 adjustably carried by the frame 5. The driving shaft 15 is rotated in timed relation with the wrapping mechanism as will be hereinafter described and the booster roll 217 is rotated at a uniform rotational velocity in synchronism with the rest of the machine preferably having a peripheral linear velocity greater than the average rate of feed of wrapping material.

After passing under the booster roll 217 the respective sheets of wrapping material from the several rolls are led through the same path and from this point onward the feeding and manipulation of the wrapping material through the various wrapping stages is the same as if but a single roll of wrapping material were employed. It will be referred to as a web or sheet and indicated by the letter W. The path of the wrapping material from the booster roll 217 is shown in diagrammatic form by Fig. 44. However, the construction and relationship of the various parts is best illustrated in Figs. 5 and 7. From the booster roll 217 the web W passes over a slack take-up roller 225, thence under a stationary idling roller 226 and next between a pair of feed rollers 227 and 228.

This path of the web is over a wrapping material tray or apron 230 (Fig. 22) supported between the side frames 5 and 6 of the wrapping machine. One end is carried by cross member 231 extending between bosses 232 of the side frames. Adjacent the wrapping material feed roller 228 the tray 230 is carried by double angle brackets 233 (Figs. 5 and 7) secured to the cross member 10 and bolted to a transverse member 234 fastened to the under side of the tray 230. The tray 230 is substantially tangent to the upper surface of the feed roller 228 adjacent the portion thereof which is engaged by the upper feed roller 227. Along the marginal portions of the tray 230 are reinforcing angle members 235 which give strength and rigidity to the tray and serve to support the rollers 225 and 226. The latter roller is journalled to be freely rotatable in brackets 236 secured to the reinforcing members 235 and arranged so that the roller is positioned transversely of the tray 230 and spaced from the upper surface thereof.

A pair of bell crank levers carry the wrapping material slack roller 225 at the extremities of their longer arms 237 and are pivoted at 238 in brackets 239 secured to the reinforcing members 235 of the tray 230. The short arms 240 of the bell crank levers are joined by a transverse bar 241 so that the pivotal movement of the levers is synchronized to carry the slack roller up and down and maintain it in constant parallel relation with respect to the booster roll 217 and idling roller 226. Tension spring 242 is connected to a central portion of the transverse bar 241 and extends toward the rear of the machine, being secured to the cross member 231. This spring normally tends to rotate the bell crank levers in a clockwise direction, as viewed in Figs. 5, 7 and 44, about the pivots 238. Upward movement of the bell crank levers is limited by depending lugs 243 of the cross member 7 which engage the extremities of the long arms 237 in which the slack roller 225 is journalled. Other methods of limiting this upward movement of the slack roller 225 may be employed such for example as by arranging the transverse bar 241 so that it engages the lower

edges of the reinforcing angle members 235 when the desired upward limit of movement of the roller 225 is reached.

A latch 243 (Fig. 3) is pivoted to the side frame 6 adjacent the path of the long arm 237 of one of the slack roll bell crank levers. This latch may be swung inwardly to engage the arm 237 when the latter is adjacent the wrapping material tray 230, thus holding the slack roller 225 down near its lower limit of movement. In this position the threading of a web of wrapping material into the machine over the roller 225 is easily accomplished.

The wrapping material smoother or bottom feed roller 228 is of considerably greater diameter than the top feed roller 227. It comprises a tubular member 244 (Fig. 21) of a suitable material, such as steel, carried on a pair of end members or hubs 245 secured to a shaft 246 journaled at 248 in the side frames.

The top or small feed roller 227 is mounted above the tubular member 244 of the feed roller 228 and at spaced intervals has circumferential bands 250 of soft, yieldable and elastic material, such as rubber, to frictionally engage the feed roller 228. Reduced diameter end portions 251 (Fig. 21) of the top feed roller are carried in spring mounted journals 252 threadedly engaged and supported by guide pins 253. These pins are carried in upstanding brackets 254 which have upper and lower extensions 255 and 256 respectively. The guide pin 253 has sliding engagement with the lower extension 256 and an adjusting sleeve 257 threadedly engaged in an aperture in the upper extension 255. This sleeve slidingly receives the upper portion of the guide pin 253 and a compression spring 258 retained by the sleeve seats against a collar 259 on the guide pin. Accordingly, by screwing the adjusting sleeve 257 up or down the pressure exerted on the top feed roller 227 by the journal 252 may be regulated so that the frictional engagement between the annular rubber bands 250 and the tubular member 244 may be adjusted. One end of the shaft 246 of the bottom feed roller extends beyond the journal 248 in the side frame 6 and has a gear 260 keyed thereto. The reduced diameter portion 251 at the corresponding end of roller 227 extends beyond the bushing 252 and has a gear 261 keyed thereto and meshing with the gear 260. The gears 260 and 261 are provided with the proper number of teeth so that the bands 250 and tubular member 244 may be synchronously rotated at substantially the same peripheral speed in opposite directions by rotation of the shaft 246.

A stripper 263 is positioned above and in spaced relation with the end of the tray 230 adjacent the bottom feed roller 228. This stripper is carried by a supporting member 264 extending across the tray 230 and having depending flange portions 265 secured to the reinforcing angle members 235. A plurality of finger portions 266 formed on the stripper extend between the top and bottom feed rollers and between successive bands 250. A bed knife supporting member 268 is positioned adjacent the bottom feed roller 228 on the opposite side thereof from the tangentially disposed end of the tray 230 (Fig. 6). This knife support is carried between the side frames of the machine and has a concave side corresponding to the contour of the smoothing roll 228 disposed adjacent the latter so that the upper surface of the supporting member is substantially tangential with the line

of intersection of the feed rollers. The support 264 is angularly disposed with respect to the plane of the tray 230 so that the tray and stripper 263 converge toward the bight of the feed rollers, thus facilitating the initial feeding of an end of a web W between the rollers when introducing a new supply of wrapping material. The fingers 266 of the stripper extend a substantial distance beyond the feed rollers and overlie the upper surface of the supporting member 268, and in close proximity thereto so that the leading edge of the wrapping material is closely guided therebetween.

At the side frame 5 the shaft 246 of the bottom feed roller extends a substantial distance beyond the journal 248 and at its extreme end carries a hand wheel 270. This wheel (Fig. 20) has a hub 271 longitudinally slideable on the shaft 246 and secured against rotation by a key 272. A hub cap 273 seats against the end of the shaft 246 and is retained in fixed relation with respect thereto by a collar bolt 274 which threadedly engages the shaft. By rotation of the hub cap 273, rotatable on the collar bolt 274 and threadedly engaging the hub 271, the hand wheel 270 may be advanced or retracted with respect to the shaft 246 thus providing accurate longitudinal adjustment, later described.

The hand wheel 270 is in spaced relation with respect to the side frame 5 to accommodate a clutch sleeve having a radially disposed flange 275 on the end thereof adjacent the hand wheel. This sleeve is freely rotatable on the shaft 246 and has an anti-friction bushing 276. A sprocket 277 having an elongated hub portion is carried by the clutch sleeve and secured thereon against relative rotation by a key 278. Intermediate the sprocket 277 and radial flange 275 the clutch sleeve carries a circumferential collar 279 which has an inwardly extending peripheral flange 280. A ball thrust bearing assembly 281 between the radial flange 275 and the peripheral flange 280 of the collar 279 is carried by the clutch sleeve and disposed within the circumferential collar 279. The side of the flange 280 opposite the thrust bearing seats against an annular collar 282 carried by an elongated hub portion of the sprocket 277. This sprocket is connected by a chain belt 283 (Fig. 4) to a driving sprocket (not shown) secured behind the sprocket 223 previously mentioned on the continuously rotating driving shaft 15. The clutch sleeve flange 275 is provided with a toothed clutch disc element 284 and a mating toothed clutch disc element 285 is carried by a radial flange 286 formed on the hub 271 of the hand wheel 270. These clutch elements have opposing faces provided with fine radially extending teeth 287 (Fig. 25). The direction of rotation of the sprocket 277 and the configuration or slope of the faces of the teeth 287 are such that when the clutch elements are brought into engagement a driving connection is established between the driving shaft 15 and the wrapping material feeding rollers 227 and 228 so that the latter are rotated to feed wrapping material from left to right as viewed in Figs. 5, 7 and 44.

Internally threaded, radially directed, top and bottom bosses 288 diametrically opposed to one another are formed on the annular collar 279 (Figs. 21 and 25) to receive bolts 89 positioned in apertures formed in the ends of a yoke 290 carried on one end of a clutch actuating lever 291. This lever is pivoted on stud 293 between top and

bottom portions of bracket 292 extending from the side frame 5 of the machine adjacent the shaft 246. The oscillation in a horizontal plane of the clutch actuating lever 291 is controlled in a manner to be hereinafter described, and brings the clutch element 284, driven at a constant rotational velocity by the sprocket 277, into and out of engagement with the clutch element 285 secured to the shaft 246, thus starting and stopping the wrapping material feed rolls 227 and 228.

When the clutch elements 284 and 285 are disengaged, the feed rolls 227 and 228 may be freely rotated in either direction by the hand wheel 270. This feature aids in initially threading a web of wrapping material into the machine and in changing wrapping material supply since the clutch is normally disengaged and the operator can release the grip of the feed rolls on the old web and introduce the new web between them with a minimum of effort and time.

For supporting wrapping material advanced by the feed rolls 227 and 228 an apron 294 is provided (Figs. 5, 7, 9 and 16). This apron, preferably constructed of a material such as sheet steel or aluminum, is positioned between the side frames of the machine and, from a position slightly below and spaced from the edge of the bed knife supporting member 268, slopes downwardly and away therefrom in the direction of web feed. The upper end thereof adjacent the supporting member 268 is carried on a pair of brackets 295 secured to the cross member 10. Depending stirrup portions 296 of the brackets accommodate a wrapping material carrier bar at the lower end of its path, as will be hereinafter described. The opposite or lower end of the apron 294 is carried on a rod 297 (Fig. 9) extending between and supported by the side frames 5 and 6.

A spring pressed pivoted scraper plate 298 (Fig. 5) is secured to an angle member apertured to receive upwardly extending pins 299 held in horizontal portions of the double angle brackets 233. The angle member has downwardly directed knife edges bearing on the brackets 233 adjacent the pins 299 and the scraper 298 is thus urged upwardly against the bottom of the large feed roll 228 to remove foreign particles such as wax from the wrapping material web W.

Wrapping material positioning

At the instant the clutch actuating lever 291 causes engagement between the clutch elements 284 and 285 to commence the feeding of wrapping material, upper and lower wrapping material carrier bars 300 and 301, respectively, are in approximately the position indicated in Figs. 5 and 55. These carrier bars are thus below the line of feed of the wrapping material, so that the leading edge of the wrapping material passes over the carrier bars and is initially supported by the apron 294.

The bars 300 and 301 are positioned in parallel relation with one another and with the web W, transversely of the direction of feed of the wrapping material and parallel with the plane of the apron 294. They are carried by a pair of spaced parallel pivoted arms 302 (Fig. 9) having hubs 309 clamped on an oscillating shaft 303 journaled in the side frames. Oscillatory motion is imparted to the shaft 303 and the carrier bars by a depending lever 304 (Fig. 3) having one end secured to the shaft 303 and op-

posite end 305 connected by an L-shaped link 306 to an oscillating lever 307 secured on an oscillating driving shaft 16 (see also Fig. 28). One limit of movement of the shaft 16 and lever arm 307 is indicated in Fig. 3, in which position the arms 302 are in their uppermost position. The other limit of movement carries the arms 302 to their lower position indicated in Figs. 5 and 44. End portions 308 are formed on the pivoted arms 302 and set at an acute angle with respect to the main portions. The lower carrier bar 301 is journaled in the arms 302 adjacent the point at which the end portions 308 are joined to the main portion of the lever, while the upper carrier bar 300 is journalled in the extremities of the end portions 308. Because of the acute angle between the end portions 308 and the main portion of the lever, the radii of oscillation of both the upper carrier bar 300 and the lower carrier bar 301 about the shaft 303 are substantially equal.

Extending from the hubs 309 of the carrier bar arms 302 are ears 310 each having an arm 311 pivoted thereto at 312. Stirrups 314 (Fig. 10) are formed on the ends of arms 311, the latter being positioned on the inside of the carrier bar arms 302. At 315 each of the arms 311 crosses the arm 302 to which it is pivoted and the stirrup is positioned about the angularly disposed end portions 308 of the arms 302. Accordingly, free ends 316 of the arms 311 are disposed adjacent the end portions 308 of the arms 302 and on the inside thereof. Pins 317 secured in the free ends 316 carry a clamping bar 318 which thus extends between the arms 311 and is in parallel relation with respect to the carrier bars 300 and 301.

In addition to the oscillatory movement of the clamping bar arms 311 about the shaft 303, they have a supplementary oscillatory movement about the pivots 312, which are offset with respect to the shaft 303. The position of the pivots 312, carried by the ears 310 of the lever arms 302, is such, with respect to the axis of the lever 302 and the axis of the shaft 303, that the clamping bar 318 is maintained in parallel relationship with the carrier bars 300 and 301. At the lower limit of movement of the arms 311 the clamping bar 318 engages the carrier bar 301, so that the two may cooperate to grip a sheet of wrapping material positioned across the carrier bar 301. Pivotal movement of the arms 311 about the pivots 312 causes the clamping bar 318 to move away from the carrier bar 301, thus releasing the wrapping material gripped between the two. During oscillation of the arms 311 about the pivots 312 the gripper bar 318 is carried outwardly past the carrier bar 300 without engaging the latter, so that there is no gripping action between the upper carrier bar 300 and the clamping bar 318.

While the carrier bars 300 and 301 move downward to the position shown in Fig. 5, the gripper bar 318 is brought to rest above the level of the stripper 263. Rollers 320 (Fig. 10), are rotatably carried by collared screw bolts 321 secured in the clamping bar arms 311 at the portions thereof positioned outside the carrier bar arms 302. As the shaft 303 is oscillated counterclockwise, as viewed in Fig. 9, to carry the arms 302 and 311 downward, the rollers 320 engage cam brackets 322 secured opposite each other on the side frames, thus arresting the arms 311 which then turn on the pivots 312 as the arms 302 continue downward movement.

The roller engaging edges of the cam brackets 322 are formed to gradually arrest the movement of the clamping bar 318, with the latter finally brought to rest above the plane of wrapping material feed, and parallel therewith. The clamping bar 318 remains in this position until it is engaged by the lower carrier bar 301 upon upward movement of the latter. This upward movement of the carrier bars occurs after the wrapping material feed has been commenced by the rollers 227 and 228 so that the underside of the advanced wrapping material is engaged by the carrier bar and carrier upwardly, and the gripper bar 318 serves to clamp the wrapping material in cooperation with the carrier bar 301.

Positioned slightly below and to the rear of the oscillating shaft 303, and in parallel relation therewith, is a second or auxiliary oscillating shaft 323 (Figs. 3 and 9). This shaft carries the idling sprocket 128 rotatable thereon and previously mentioned in connection with the infeed conveyor driving chain 123. Oscillatory movement is imparted to the shaft 323 by a lever 324 secured on an end thereof extending beyond the side frame 6. A link 325 connects an end of the lever 324 to the end of driving lever 326 secured on a portion of the oscillating drive shaft 17, which extends outwardly of the side frame 6. In a manner to be hereinafter described the drive shafts 16 and 17 are oscillated in synchronous timed relation, so that the shaft 323 is oscillated in timed relation with respect to the shaft 303 carrying the arms 302 and 311. Cam levers 327 are secured to the shaft 323 for synchronous oscillation in spaced parallel relation with one another through arcuate paths. The cam levers move in the same planes as the gripper bar arms 311, and the oscillation of the shaft 323 is of sufficient degree and timed with respect to the oscillation of the shaft 303 so that upon the carrier bar lever arms 302 reaching their upper limit of movement (carrying the clamping bar arm 311 because of the engagement between the clamping bar 318 and carrier bar 301), the cam levers 327 engage the clamping bar arms 311 and move the latter in a slight additional upward oscillatory movement about the pivots 312, thus disengaging the clamping bar 318 from the carrier bar 301 for a purpose to be hereinafter pointed out. However, before, the carrier bar 301 has made any substantial downward movement, due to oscillation of the shaft 303 in a counterclockwise direction as viewed in Fig. 9, the cam levers 327 are oscillated by the shaft 323 out of engagement with the clamping bar arms 311, so that the clamping bar 318 reengages the carrier bar 301 to grip the wrapping material web.

Article measuring mechanism

As an article is advanced over the apron 110 toward the infeed station of the wrapping machine it engages an article size indicator having a plurality of depending bars or fingers 400 (Figs. 9 and 19). These fingers are carried in a bracket 401 secured to a pivot bar 402. This bar is supported by brackets 403 and 404 secured respectively to the supporting member 101 on the operator's side of the machine and the supporting member 100 on the opposite or drive side. Preferably each of these brackets has a ball bearing journal, indicated by numeral 407 in Fig. 24, to receive an end of the pivot bar 402 in order that the latter may rotate with a mini-

mum of friction. The pivot bar 402 is supported with its axis at substantially a right angle with respect to the direction of movement of articles over the infeed conveyor and a sufficient distance above the apron 110 so that the largest articles intended to be packaged by the combination will have adequate clearance thereunder. The fingers 400, however, are of sufficient length to extend substantially below the upper extremities of the auxiliary pushers 115 when the latter are in article-advancing position and are arranged to pass between the auxiliary pushers 115 through the spaces 120 previously mentioned (see Fig. 19).

A latch mechanism illustrated in detail in Figs. 23 and 24 is carried by the pivot bar 402. This latch comprises a quadrant 405 positioned transversely of the axis of the pivot bar and rotatably carried on the latter by a hub 406. The hub 406 is positioned on the end of the pivot bar 402 adjacent the ball bearing journal 407 of the bracket 403 and held against longitudinal sliding on the pivot bar by a clamping hub member 409 which is secured to the pivot bar 402 by means of a tightening bolt 410. Extending radially from the hub 409 is an arm 411 having an aperture in its extremity to slidably receive the threaded end of an adjusting bolt 412. The opposite end of the bolt 412 is threadedly secured in an extension 414 on the quadrant member 405. A knurled thumb nut 415 carried on the threaded end of the adjusting bolt 412 enables the quadrant 405 to be rotated slight amounts about the axis of the pivot bar 402 and a compression spring 416 positioned between the arm 411 and extension 414 urges the arm against the thumb nut so that the quadrant 405 is retained in adjusted position with respect to the pivot bar 402.

Referring to Fig. 18 the clutch actuating lever 291 is urged toward side frame 5 by a compression spring 418 carried on a rod 419 extending through an aperture in the lever 291 and screwed into the side frame. Beyond the rod 419 the clutch actuating lever 291 extends upwardly and is bifurcated at 420 to receive a tie rod 421. This end of the tie rod is threaded to receive a pair of nuts which are disposed on opposite sides of the lever 291. A compression spring 422 is carried by the tie rod 421 between the outer nut and the lever 291. The tie rod 421 extends through apertures in the side frame 5 and supporting members 100 and 101, and terminates in a clevis 423 adjacent the bottom portion of the bracket 403 secured to the supporting member 101.

Pivoted at 424 to the bracket 403 is a latch lever 425 having an angularly disposed arcuate shaped foot 426 with its center of curvature at the pivot. Heel 427 of the lever normally engages a marginal portion of the quadrant 405 and retains the latch 425 in an upright position as indicated by the full lines of Fig. 19. The end of the latch opposite the foot 426 is pivoted in the clevis 423, and the end of the clutch actuating lever 291 engaged by the end of the tie rod 421 is held outwardly away from the side frame 5 against a compression of the spring 418. In this position the clutch elements 284 and 285 are disengaged so that there is no driving engagement between the sprocket 277 and the wrapping material feed rolls 227 and 228. The position of the quadrant 405 on the pivot bar 402 is arranged so that when the wrapping material advancing clutch is thus held in disengaged position the fingers 400 are suspended in

article engaging position over the infeed conveyor apron 110.

Upon being engaged by an article moving over the conveyor apron 110 the fingers 400 are rotated in a clockwise direction as viewed from the operator's side of the machine (see Fig. 3). This movement of the fingers 400 rotates the pivot bar 402 in a counterclockwise direction as viewed in Fig. 23. Upon sufficient movement in this manner the radial or latch releasing edge 428 of the quadrant 405 moves beyond the heel 427 of the latch lever 425 so that the latter is released and moves to the broken line position indicated in Fig. 19. This movement of the latch lever is energized by the compression spring 418 through the clutch actuating lever 291 and tie rod 421. Movement of an article past the ends of the fingers 400 releases the latter and they fall or rotate downwardly by gravity. The foot 426 of the latch lever 425 engages the edge 428 of the quadrant to prevent the latter from moving past the latch lever in the event that the latter has not been returned to its vertical position, as will be hereinafter described. Release of the latch lever by the quadrant 405 permits the clutch actuating lever 291 to pivot at 293 under the influence of spring 418 and slide the clutch sleeve along the shaft 246 thus engaging the clutch elements 284 and 285 to energize the feed rolls through the sprocket 277 and chain belt 283.

The feed rolls 227 and 228 advance wrapping material over the bed knife supporting member 268 until the long arm of the clutch actuating lever 291 is moved outwardly away from the side frame 5 to disengage the clutch elements 284 and 285. This disengagement of the clutch is accomplished by an arm 430, Fig. 25, which moves in an arcuate path and carries on its extremity by means of a pin 431 a pair of coaxial rollers 432 and 433. As the lever 430 moves to the position shown in Fig. 25 the roller 432 engages a cam member 434 adjustably mounted on bracket 435. The bracket 435 is secured to the clutch actuating lever 291 adjacent the compression spring rod 419 and arranged so that the cam member 434 faces toward the side frame 5. On the frame opposite the cam member 434 is secured a cam roller guide 437 (Fig. 18) which is engaged by the roller 433. The cam member 434 and the cam roller guide 437 are arranged so that upon movement of the clutch release arm 430 into the position illustrated in Fig. 25 the clutch actuating arm 291 is kicked outwardly away from the side frame 5 sufficiently to disengage the clutch elements 284 and 285 and move the tie rod 421 to the right as viewed in Fig. 19, so that the latch lever 425 is raised from the broken line position to the solid line position. This pivotal movement of the latch lever carries the foot 426 and heel 427 thereof beyond the latch releasing edge 428 of the quadrant 405, thus permitting the pivot bar 402 to rotate to its normal position as the fingers 400 previously released by the article fall by gravity to a substantially vertical position. Upon movement of the clutch release arm 430 from between the cam member 434 and cam roller guide 437, the clutch actuating arm 291 is retained in its outer position by the tie rod 421 which is held to the right as viewed in Fig. 19 against the compression spring 418 by the latch lever 425 which is held in its vertical solid line position by the quadrant 405 again positioned in front of the heel 427 of the latch lever.

The reciprocable arcuate movement of the clutch arm 430 is timed with respect to the remainder of the wrapping machine mechanism so that it disengages the feed roller clutch prior to the severing of the wrapping material web. This release arm is carried by a pivoted lever which is associated with the wrapping material severing mechanism and the movement will be described in connection therewith. Since the movement of the arm 430 is synchronized with the remainder of the wrapping machine mechanism it operates to stop the wrapping material feed at a definite point in the wrapping cycle and a flight advancing an article on the infeed conveyor past the fingers 400 is in a definite position with respect to the infeed station and fingers. Referring to Figs. 26 and 27, the numeral 440 indicates the position of a flight 113 when the clutch release arm 430 engages the cam member 434 to disengage the clutch elements 284 and 285. The manner in which the loaf measuring mechanism is arranged to control the wrapping material feed to advance a length of wrapping material proportioned in accordance with both the height and width of the article will now be described.

The quadrant 405 is adjusted on the pivot bar 402 so that the latch lever 425 is released when the article engaging fingers 400 are moved to a substantially angular position with respect to their normal vertical position. A suitable angle has been found to be from 15 to 45°, preferably about 20 to 25°, as indicated by the solid lines (Figs. 26 and 27). Now, assuming a loaf F, indicated by the solid line in Fig. 26, is being advanced over the infeed conveyor apron, indicated at 110, by the infeed conveyor flight 113 toward the infeed station of the wrapping machine and in the direction indicated by the arrow 441; the article F first engages the fingers 400 when they are in the substantially vertical position indicated by the broken lines. Upon further movement of the article the fingers are rotated to the solid line position, at which instant the latch releasing edge 428 of the quadrant 405 moves beyond the heel 427 of the latch lever 425, releasing the latch and enabling the compression spring 418 to move the clutch actuating lever 291 so that the clutch elements 284 and 285 are instantaneously engaged to commence the feed of wrapping material between the rolls 227 and 228. Since the clutch elements are toothed the driving action is positive and the feed rolls are started at substantially full speed. Longitudinal movement of the handwheel 270 on the shaft 246 adjusts the relative positions of the clutch elements. This is accomplished by the hub cap 273 and insures the making and releasing of the driving connection upon movement of the lever 291. The clutch elements remain in engagement to advance the free edge of the wrapping material as the flight 113 moves the article F over the infeed conveyor apron 110 to the broken line position F' at which instant the wrapping material feed stops because the clutch release arm 430 engages the cam member 434, swinging the clutch release lever 291 on its pivot 293 and disengaging the feed roll driving clutch. Meanwhile the fingers 400, released by the article, swing by gravity to their vertical position, and, upon movement of the clutch release arm 430 away from the cam member 434, the feed roll clutch is held disengaged.

As previously mentioned, the movement of the clutch release arm 430 is timed with relation to

the infeed conveyor flights 113 so that it operates to disengage the feed roll clutch each time a flight reaches the position indicated at 440. Accordingly, the leading edge of the wrapping material web W has been advanced by the feed rollers 227 and 228 during the interval of movement represented by X, since the flight 113 was in the position 442 at the instant the latch lever 425 was released and in position 440 at the instant the clutch release arm 430 disengaged the clutch. If an article G, represented by the broken lines in Fig. 26, is being advanced to the infeed station of the wrapping machine by a flight 113, the latch lever 425 is released by the quadrant 405 to permit engagement of the clutch in the start of wrapping material feed when the flight is in the position indicated at 443. The article G is of substantially greater width than the article F, and accordingly, the fingers 400 are moved to latch releasing position before the flight advancing the article has moved as close to the wrapping material feed arresting position 440 as in the case of a narrow article. Thus the sheet of wrapping material advanced by the feed rollers to wrap the article G is continuously fed while the flight 113 moves the distance represented at Y. By comparing the distances X and Y, it is seen that the comparative wrapping material feeding times for the articles F and G are in proportion in relation to their respective sizes so that the sheet of wrapping material intended for the article G is fed for a longer period of time than the sheet of wrapping material for the article F. Since the rate of wrapping material feed is substantially uniform and in timed relation with the remainder of the wrapping machine mechanism, including the infeed conveyor, the length of wrapping material fed is likewise proportioned in accordance with the size of article being advanced to the wrapping mechanism.

Similarly, the length of wrapping material advanced by the feed rollers is proportioned in accordance with the height of the article, as diagrammatically illustrated in Fig. 27. For the tall article R, shown in solid lines, the flight 113 advancing the article is at the position 444 at the instant the fingers 400 release the latch lever 425 and the feed roll clutch remains in engagement to advance the wrapping material while the flight moves the distance U from the position 444 to the position 440. The short article S is advanced by the flight 113 only the distance Z from the point 445 at which the fingers 400 are moved to their latch releasing position to the point 440, which is the clutch disengaging position. By comparison it is seen that the distance Z is less than the distance U and the corresponding wrapping material advancing period is less for the small, short article S than for the tall article R.

Because of the angular position of the fingers at the instant of latch release the flight advancing a tall or a wide article is further removed from the wrapping material feed arresting position 440 than the flight advancing a short or narrow article. Thus the invention provides a mechanism for measuring the size of articles both as to height and width and is arranged to advance a sheet of wrapping material proportioned in length in accordance with these measurements. It is apparent that this measuring mechanism is responsive to changes in either the height or width alone or height and width together. The diagrammatic representation of Fig. 26 shows articles F and G which are of substantially the same height, and Fig. 27 diagrammatically illus-

trates the difference in the wrapping material feed periods for articles of different height but of substantially the same width. A dog 446 carried by the arm 411 is arranged to engage an inwardly extending lug 447 on the bracket 403 which is formed adjacent the journal 407 to prevent overswinging of their normal substantially vertical position by the fingers 400 after being released by an article.

10 The adjustment between the relative position of the article engaging fingers 400 and the latch releasing edge 428 of the quadrant 405 afforded by the adjusting bolt 412 and knurled thumb nut 415 provides a convenient means for adjusting 15 the amount of the overlap of the ends of the wrapping material underneath the article. Drawing the extension 414 of the quadrant 405 toward the arm 411 causes the quadrant to release the latch lever 425 sooner after fingers 400 are engaged by an article so that the feed of wrapping material is commenced earlier. Conversely, adjustment of the thumb wheel 415 to cause divergent movement between the arm 411 and extension 414 of the quadrant causes the quadrant 20 to withhold the latch lever 425 from clutch engaging movement until the fingers 400 have been rotated to a substantially greater angular position with respect to the vertical, thus delaying the start of wrapping material feed. Hence a sheet of wrapping material fed in response to the article measuring controls with the delayed 25 release of the latch lever 425 is relatively shorter in length than the wrapping material advanced for an article in response to the controls which are adjusted for a relatively earlier release of the latch lever 425. A relatively short length of wrapping material will have less overlap of its ends than a relatively long sheet. Furthermore, this adjustment of the overlap can be accomplished while the wrapping machine is in continuous operation, without interrupting the succession of articles being packaged. An operator 30 merely gives a slight twist to the thumb nut 415 in the desired direction and visually observes the resultant change in overlap.

45 Since the movement of the clutch actuating lever 291 caused by the engagement of the cam member 434 by the release arm 430 serves only to disengage the clutch elements 284 and 285, the feed rolls are likely to continue to advance a short and variable amount of wrapping material on account of overrunning caused by their inertia. It is desirable that this overrunning be minimized so that the feed of wrapping material is positively arrested at the instant the clutch release arm 430 engages the cam member 434. In the present machine this is accomplished by a brake which engages a flattened peripheral portion 450 on the hand wheel 270. This brake 50 comprises an adjustable supporting bracket 451 (Fig. 20) having a foot 452 slidably received in a longitudinal channel formed in the clutch release lever 291 adjacent the pivot 293. A brake shoe 455 provided with a lining 456 of asbestos or other suitable friction material is carried by a cylindrical plunger 457 received within a cylindrical aperture formed in the bracket 451 and having its axis in substantially the rotational plane of the hand wheel 270. The cylindrical 55 aperture in the bracket 451 is of sufficient depth to accommodate a compression spring 458 carried by a rod 459 formed as an extension of the plunger 457 and coaxial therewith. This rod extends through an aperture in the bracket and has an external end threaded to receive a hold-

ing nut 460. The plunger 451 and rod 459 are thus movably secured by the bracket 451 and resiliently urged toward the flat friction face 450 of the hand wheel 270 by the spring 458. An extension 461 of the bracket has a flat face which engages a side of the shoe 455 to prevent rotational movement of the plunger and shoe with respect to the bracket. The clockwise pivotal movement of the lever 291 about the pivot 293 (Fig. 20) (which brings the clutch elements into engagement) moves the brake bracket 451 away from the hand wheel 270; reverse pivotal movement of the lever 291 brings the brake into engagement with the hand wheel substantially immediately after disengagement of the clutch elements 284 and 285. By adjustment of the nut 460 on the threaded end of the rod 459 the brake shoe 455 can be moved toward and away from the friction surface 450 of the hand wheel. This adjustment is regulated so that just prior to engagement of the teeth of the clutch elements 284 and 285 by the pivotal movement of the clutch actuating lever 291 the brake releases the hand wheel 270. Thus there is a substantially positive control of the feed rollers so that the wrapping material is accurately advanced during an interval which is determined in accordance with the size of the article for which the particular sheet being advanced is intended.

Article carrier

At the infeed station adjacent the end of the infeed conveyor the articles are successively moved onto a reciprocable carrier or elevator indicated generally by the numeral 500 (Figs. 1, 2 and 3). This elevator comprises a platform 501 (Figs. 5, 7, 9, and 22) carried by a cross member 502 which extends transversely of the wrapping machine and at each end is secured to vertically sliding sleeve members 504 carried on guides 505. Tops of guides 505 are positioned in apertures in the frames 5 and 6, and the bottoms thereof are supported in sockets of brackets 506 bolted to the side frames. These guides are arranged in parallel relation with one another so that the sleeve members 504 are free to move up and down thereon in guiding the carrier 500 between the infeed and outfeed stations of the wrapping machine. This vertically reciprocating movement of the carrier is provided by the oscillating movement of the crank levers 508 which are secured on the oscillating drive shaft 16 previously referred to in connection with the carrier bars 300 and 301. The crank levers 508 are positioned on the oscillating shaft inside the side frames 5 and 6. They are each connected to one of the elongated sleeve members 504 by curved links 509 (Figs. 5 and 28). Oscillating movement is imparted to the shaft 16 in a manner to be hereinafter described and the levers 508 are secured thereon so that at the limit of the counterclockwise oscillation, as viewed in Fig. 7, the elevator 500 is in its lowermost position and the platform 501 thereof is substantially even with or slightly below the infeed station end of the conveyor apron 110 (see Fig. 9). In this position of the carrier the levers 508 extend downwardly from the shaft 16 in a substantially vertical position. Since the shaft 16 is positioned substantially directly below the guides 505 the links 509 are curved to avoid engagement with the shaft. From the position of the mechanism illustrated in Fig. 7 clockwise rotation of the shaft 16 carries the levers 508 to a substantially vertical position extending upwardly from the

shaft as illustrated in Fig. 5. This moves the carrier 500 to its uppermost position at the outfeed station of the wrapping machine. In this position the platform 501 of the carrier is substantially level with the bottom plate of the folding and heat sealing channel to be later described. Accordingly, rotation of the shaft 16 and the levers 508 through 180° moves the carrier 500 from one end of its path to the other. However, the position of the levers illustrated in Fig. 5 does not represent the limit of their movement in a clockwise direction. Movement is continued for a distance slightly beyond the vertical and the total path of each oscillation is slightly greater than 180°. For example, the diagrammatic illustration of Fig. 63 shows a suitable movement of the levers 508. The upper limit is represented by the full lines. Accordingly, a slight down and up movement of the elevator 500 occurs adjacent the outfeed station of the wrapping machine after the carrier reaches its uppermost position and before the carrier starts its downward movement to the infeed station. During operation of the machine this slight movement of the carrier is hardly perceptible by an observer but serves to prolong the period of time during which the carrier is adjacent the outfeed station, thus affording ample time for the discharge of the article from the carrier into the folding and heat sealing channel.

A plurality of ribs 510 facilitate the movement of an article onto and off the carrier. These ribs may be suitably formed of wires or rods which are arranged in parallel relation to one another and extend in the direction of movement of the articles. The ends of the ribs are bent downwardly and secured in apertures in the platform 501 to retain the ribs in position.

Along the edge of the platform 501 over which articles are moved onto and off the carrier is positioned a roller 511, the top of which is substantially level with the top surface of the platform 501. The ends of this roller threadedly receive axially aligned pins 512 which are carried in journals 514 secured to the ends of the platform 501. Accordingly, the roller 511 extends entirely across the edge of the carrier and facilitates movement of an article onto and off the carrier.

At a central portion of the platform 501 at the edge thereof opposite the roller 511 are secured brackets 515 (Figs. 7 and 22) which carry elongated tubular sleeves 516 arranged in parallel relation. The sleeves 516 carry rods 517 longitudinally slidable in the direction of movement of articles onto and off the carrier and the rods are secured together for simultaneous movement by a tie 518. The ends of the rods opposite the tie carry flat article engaging members 519 (Fig. 16) which may suitably be formed of rectangular metallic plates. Upon movement of an article onto the carrier these plates engage the side thereof and move with the article, the rods 517 meanwhile sliding in the sleeves 516 to a position which may be represented by the broken lines in Fig. 22, depending upon the width of the particular article.

Intermediate each end of the platform 501 and the brackets 515 is a movable support 520. This support has a portion which slides along the surface of the platform and a portion 521 which overhangs the rear edge of the platform. This portion 521 has secured thereto a gib 522 which underlies the edge of the platform and is formed around a key guide 523 secured along the under side thereof. Engagement between the guide and

gib retains the support 520 on the platform 501 while permitting transverse movement thereof along the rear edge. Each of the supports 520 has secured thereto a first end fold finishing member 525 which extends over the platform 501 toward the edge thereof over which articles are received. These end folders may suitably be formed of substantially flat elongated metal plates which have their article engaging ends 526 rounded in contour and beveled inwardly from the tip toward the article engaging face of the folder (see Fig. 22). Each of the end folders is positioned so that its flat side is substantially vertical and the bottom edge of the member is parallel with and in spaced relation with respect to the platform 501.

An adjusting shaft 527 has oppositely threaded ends engaged in apertures through the overhanging portions 521 of the movable supports 520. Thus by rotation of a knurled hand wheel 528 secured on one end of the shaft 527 the brackets may be simultaneously moved toward and away from one another thus adjusting the distance between the first end folding members 525. The shaft 527 is retained against endwise movement by a bracket 529 secured to the platform 501 at one end thereof and having a yoke which engages a circumferential groove in the hub 530 of the hand wheel 528.

Each of the movable supports 520 has an upstanding portion 531 terminating in a sleeve 532 (Fig. 7) carrying a pin member 533 secured to a central portion of a lever arm 534 (Fig. 16). Lower extremities of the lever arms 534 carry end fold starters 535 formed of rods or bars normally extending parallel to and in spaced relation with the platform 501. The extremities of the end fold starters 535 adjacent the ends 526 of the end folding members, are formed into inwardly disposed wrapping material guides 536 (Fig. 22) which form acute angles with the body portion 535 and terminate adjacent the ends 526 of the folders 525. Preferably the initial wrapping material engaging portion 537 of the end fold starters is positioned substantially directly above the edge of the carrier over which an article is received, so that this portion of the end fold starter engages the wrapping material extending beyond the end of the article simultaneously with the engagement thereof by the roller 511. Thus the projecting portion of the wrapping material is first engaged by the rounded end 537 of the end fold starters to commence a first end folding operation and the wrapping material then is moved gradually against the end of the article by the guide portion 536 and finally by the end folding member 525, so that the folding action is smooth and gentle.

Pins 547 secured in ends of the lever arms 534 opposite the fold starters 535 are engaged by stationary overhanging stops 538 as the carrier 500 moves upwardly to the outfeed station (Figs. 5, 31 and 32). These stops are carried by brackets 539 secured to the cross member 11 and are arranged to rotate the lever arms 534 about the pin members 533 in the sleeves 532 to carry each of the end fold starters 535 outwardly and upwardly away from the first end folding members 525. This movement of the end fold starters away from the ends of the articles does not occur until the carrier is approaching the outfeed station and after the function of the end fold starters in commencing the first end folding operation has been completed. In this manner the end fold starters are removed from adjacent the ends of

the articles to permit the top end folding operations to be performed on portions of wrapping material projecting from the top of the article as will be later described. Fig. 55 diagrammatically illustrates this movement of the end fold starters. The solid lines indicate the position of the lever arms 534 during movement of an article onto the carrier and until just prior to the engagement of the pins 547 with the stops 538. The broken lines indicate the position of the end fold starters and lever arms 534 as the carrier 500 approaches its upper limit of movement and the stops 538 have depressed the pins 547 with respect to the sleeves 532 so that the lever arms 534 have been carried to a substantially horizontal position.

In order that the end fold starters will positively break or commence the first end folds and not be moved away from their normal position adjacent the first end folding members 525, coil springs 540 carried by portions of the pin members 533 extending from the sleeves 532, have one end secured to lateral extensions 541 on each of the sleeves 532 and the other end secured in a groove or notch formed in the head of each of the pin members 533. These springs exert a twisting force on the pins 533 which tend to rotate the lever arms 534 downwardly to carry the end fold starters into their normal position adjacent the first end folding members. Stops 542 (Figs. 7 and 16) formed on the upstanding portions 531 of the supports engage the lever arms 534 when the end fold starters 535 are in proper position with respect to the first end folding members. These stops limit movement of the lever arms and end fold starters induced by the springs 540, and, accordingly, the end fold starters are at all times accurately positioned on the carrier since the coil springs retain the levers 534 against the stops 542 except during the interval during which the end fold starters are moved upwardly and outwardly by engagement of the pins 537 with the stops 538.

Tight and loose wrap adjustment

Upon reaching its upper limit of movement at the outfeed station of the wrapping machine the roller 511 extending along the edge of the platform 501 engages a roller 550 (Figs. 5, 7, 13 and 14). This roller has pins 551 threadedly secured in its extremities and journaled in elongated slots 552 in the ends of bracket members 553. These brackets extend from the cross member 11 supported between the side frames of the machine and are adjustably secured thereto by screw bolts 554 which pass through elongated openings 555 (Fig. 14) in the brackets 553. Upon movement of an article to the outfeed station of the wrapping machine upon the carrier 500 the portion of wrapping material draped over the article and suspended from the rear side thereof is engaged between the rollers 511 and 550. Since the rollers are in juxtaposition throughout their entire length and across substantially the entire width of the carrier and outfeed station, the wrapping material is gripped between them throughout its entire width.

A pressure roller 557 positioned centrally of the path of articles moving past the roller 550 is journaled in a yoke 558 (Fig. 57) formed on the end of a member 559 slidably carried by a guide bracket 560 secured to the under side of the cross member 11. One end of a compression spring 562 (Fig. 13) engages an end 563 of the member 559 opposite the yoke 558. The oppo-

site end of the compression spring is carried by a lever 564 pivoted at 565 on a bracket 566 carried by cross member 12. The free end of the lever 564 which extends over the side frame 6 to the operator's station is formed into a ball knob 567. By manually moving the lever 564 to various positions, the compressive force in the spring 562 may be regulated as desired and pin 568 secured in the lever arm 564 is arranged to be selectively introduced into any one of a plurality of holes 569 formed in the side frame 6 to retain the lever 564 in adjusted position.

The spring 562 urges the yoke carried roller 557 against the central portion of the wrapping material engaging roller 550 so that this roller is resiliently forced against its mating roller 511 journaled on the carrier. The pressure roller 557 is of relatively short length with respect to the wrapping material engaging roller 550 to urge the central portion of the latter against the roller 511 with a greater force than end portions. In this manner the roller 550 being slightly yieldable along its longitudinal axis the roller 511 of the carrier and roller 550 at the outfeed station are arranged to resiliently engage wrapping material positioned between the two with the greatest frictional engagement occurring at the central portions of the rollers. Accordingly, rotation of the rollers is effected by the movement of wrapping material passing between them and gripped at their central portions. Moving the lever 564 to the right as viewed in Fig. 13 increases the frictional grip on the wrapping material by the rollers 511 and 550, while movement of the lever so that one of the holes 569 to the left, as viewed in Fig. 13, is engaged by the pin 568, decreases the frictional grip or engagement of the wrapping material by the rollers.

The elongated journal slots 552 permit slight lateral or sidewise movement of the roller 550 for prolonged engagement thereof with the roller 511. Thus there may be a slight back and forth movement of the pivot pins 551 in the slots 552 as the roller 550 follows the contour of the roller 511.

During movement of an article from the carrier 500 into the folding and sealing channel of the wrapping machine, the portion of wrapping material depending from the article is drawn between the carrier roller 511 and the spring 562 pressed roller 550 as the article moves over the latter. This movement of the wrapping material may rotate the rollers on account of the positive engagement of the wrapping material at the central portion thereof. Since the rollers extend entirely across the carrier and outfeed station, the wrapping material is engaged throughout its entire width and the marginal portions of the wrapping material which extend beyond the ends of the article have an upward feeding action exerted thereon by the marginal portions of the rotated rollers. Thus all portions of the depending or trailing end of the wrapping material are maintained in alignment so that there is less tendency for the wrapping material to become wrinkled or creased and a neater and more attractive package is produced.

Suspended from the bracket member 560 is an arm 571 (Fig. 8) which has an end received in the crotch of a yoke 572, the latter being pivotally mounted on the arm by a screw bolt 573. A freely rotatable wheel 574 provided with a relatively soft resilient tire or rim 575 which may be suitably formed of a rubber composition is journaled between the extremities of the yoke 572.

The position of the wheel 574 is such that the carrier bar 301 is engageable therewith at its upper limit of movement (Fig. 7). A tension spring 576 extending between the yoke 572 and the arm 571 urges the yoke 572 in a counterclockwise direction (Fig. 8) about the pivot 573 so that the cushioned tire 575 may be slightly compressed against the carrier bar 301. An upwardly extending finger 577 formed on the arm 571 is arranged to engage the cross member 578 of the yoke 572 to position the wheel 574 (which has a diameter substantially greater than the carrier bar) so that it engages the carrier bar 301 slightly before the latter reaches its upper limit of movement and thereby remain in contact therewith for a period of time. In this manner the wheel 574 is arranged to engage the wrapping material draped over the carrier bar 301 just prior to the disengagement of the gripper bar 318 from the carrier bar 301 and remain in contact with the carrier bar to prevent wrapping material falling therefrom until the carrier bar and wrapping material are reengaged by the gripper bar. Thus when the article in moving onto the carrier at the infeed station engages the under side of the wrapping material the upper portion of the suspended wrapping material is released by the gripper bar and yieldingly held by the wheel 574 which merely exerts sufficient pressure to prevent the wrapping material falling from the carrier bar 301 by gravity, and permits withdrawal by the article without sufficient frictional force to cause deformation of the article or tearing of the wrapping material.

Modified carrier article guide

The article engaging plates 519 carried on the spaced parallel sliding rods 517 may be replaced by a single article guiding member 580 (Figs. 35 and 36). This guiding member may be in the form of a relatively thin plate or sheet positioned in a plane at right angles to the movement of the rods 517 and secured on the ends thereof. It is made as long as possible to back up and guide an article being moved onto the carrier throughout a maximum portion of the front side of the article; the limitation on length of the plate or member 580 being the length of the smallest article to be packaged by the machine since this guide member must be reciprocable between the first end folding members 525. The lower marginal edge of the plate is formed with a curve 581 to conform to the curvature of the leading edge of the article along the bottom of the front side thereof. This curved portion serves to retain the wrapping material at this corner of the article tucked thereunder so that upon movement of the article from the carrier into the folding and sealing channel by the pusher 733 the portion of wrapping material first tucked under the article is positively advanced and does not wrinkle under the article.

Wrapping material cutting mechanism

Moving simultaneously with the carrier 500 is a cutter carriage, indicated generally by the numeral 600, (Figs. 4, 5, 16, and 22). This carriage comprises a bar or shaft 601 extending transversely of the machine and having ends secured in supporting members 602. One suitable means to secure the bar 601 is by means of a set screw 607 (Fig. 6) which is received in a threaded aperture in the supporting member 602 and engages the bar 601. These supporting members have elongated sleeves 603 slidably carried by vertically

arranged guides 604 which have their upper ends secured in apertures in inwardly extending portions 605 (Fig. 7) of each of the side frames and lower extremities secured in sockets 606 (Fig. 22) formed as inward extensions on each of the brackets 254. The guides 604 are parallel with one another and with the guides 505 for the articles carrier 500. As shown in Figs. 16 and 22 the guides 604 are slightly closer together than the guides 505 to permit the cutter carriage 600 to move through the lower portion of its path without interfering with other parts of the machine.

Knife carrier 608 on the right and knife carrier 609 on the left, as viewed in Fig. 16, are suspended from the bar 601 by collars 610 and 611 which are freely rotatable on the bar. Extensions 612 secure the knife carriers to the collars 610 and 611 so that the carriers are in accurate alignment with respect to the bar 601. The collars 610 which are at the center of the bar 601 preferably have their extensions 612 secured to the extremities of the knife carriers 608 and 609 which abut one another at this point. The collars 611 which are positioned adjacent the supporting members 602 have their extensions 612 secured to intermediate portions of the carriers 608 and 609 so that end portions 614 of the carriers overlap the supporting members 602 and extend substantially to the sleeves 603. Depending flanges 615 (Figs. 6 and 17) formed along the under side of the supporting members 602 are thus positioned behind the portions 614 of the knife carriers. A bolt 616 is threadedly secured in the portion 614 of each of the knife carriers and extends through an aperture in the depending flange 615. This bolt is freely movable through the flange and a compression spring 617 carried on the bolt and retained between the flange 615 and an adjusting nut 618 tends to draw the knife carrier toward the flange 615 in a clockwise rotational movement about the bar 601 as viewed in Fig. 6. This movement is limited by an adjusting bolt 619 (Fig. 17) extending through the flange 615 and having threaded engagement therewith. This bolt seats against the knife carrier and is provided with a lock nut 620 which secures the bolt in adjusted position.

Movable knife blades 622 and 623 secured to the knife carriers 608 and 609 respectively, abut at the line 625 and the cutting edge 626 of each blade slopes downwardly from the line or edge 625. Each blade adjacent the supporting members 602 is formed into a depending lip 627 which is curved so as to be offset with respect to the plane of the knife blade. The stationary cutting blade 630 (Fig. 6) supported in a horizontal manner on a depressed marginal portion of the bed knife supporting member 268, previously described in connection with the wrapping material feed mechanism, is secured thereto by a plurality of bolts having wedge shaped heads 631. These bolt heads have the highest portion flush with the wrapping material supporting surface 269 of the member 268 and sloped downwardly toward the cutting edge 632 of the bed knife 630. This edge of the knife is beveled in the usual manner and overhangs the supporting member 268. The guides 604 are arranged so that sliding movement of the sleeves 603 of the supporting members 602 carries the movable cutting blades 622 and 623 vertically past the bed knife 630 in a wrapping material severing movement.

As previously mentioned, the cutting edge 626 of each of the movable cutters slopes downwardly

away from the central end 625 of each cutter so that the portion of each cutting edge adjacent the lip 627 first passes the cutting edge 632 of the bed knife and upon further downward movement of the movable cutter the cutting edges 626 progressively move past the cutting edge 632 toward the central portion thereof in a scissorlike shearing action. The bolt 619 is adjusted so that the cutting edge 632 of the bed knife first engages the curved portion 633 of the depending lip 627 and the movement of the reciprocating cutter blades 622 and 623 past the stationary cutter tends to rotate the collars 610 and 611 in a slight counterclockwise movement about the bar 601 as viewed in Fig. 6, thus urging the cutting edges 626 and 632 of the respective knives against each other by the compression of springs 617.

A wrapping material straightening bar or compensator 635 is positioned adjacent and longitudinally of the cutting edges 626 of the movable knife blades 622 and 623. (Figs. 5, 6, 16, and 17). This bar extends substantially from end to end of the cutter carriage 600 and has pins 636 (Fig. 6) threadedly secured in each end and carried in journals formed in the extremities of crook shaped levers 637. Each of the levers 637 is pivoted by a bolt 638 to a laterally extending ear 639 formed on the supporting member 602. The crook portion 640 of the lever 637 extends beyond the pivot bolt 638 over the top of the supporting member 602, terminating in a horizontally arranged finger 641 (Fig. 17) which threadedly receives a vertically positioned adjusting bolt 642. Intermediate the finger portion 641 and pivot 638 the crook 640 has a laterally extending boss 644 apertured to receive the end of a compression spring 645. The other end of this spring is received in a depression formed in the upper surface of the supporting member 602 and the spring urges the lever 637 in a clockwise pivoting motion around the bolt 638 as viewed in Fig. 6. This serves to normally press the compensator 635 against the knife blades 622 and 623.

The cutter carriage 600 is actuated in synchronism with the carrier 500. An outwardly extending boss 650 (Fig. 16) formed on each of the sleeves 603 projects beyond the side frames 5 and 6. Pivot bolts 651 having horizontal axes parallel with the bar 601 are journaled in actuating levers 652 (Fig. 3) and 653 (Fig. 4). The rearwardly extending ends of the levers 652 and 653 are carried by short links 654 pivoted at 655 on supports extending upwardly from intermediate members of the side frames. The opposite ends of the actuating levers 652 and 653 are carried by long links 656. These links are pivoted at 657 to intermediate portions of the curved links 509 previously described in connection with the carrier. Accordingly, reciprocable movement of the curved links 509 which moves the carrier back and forth between infeed and outfeed stations of the wrapping machine simultaneously moves the cutter carriage 600 up and down on the guides 604. The arrangement of the actuating levers 652 and 653 is such that the amplitude of movement of the cutter carriage is less than that of the article carrier 500. The actuating lever 653 which is on the drive side of the machine has formed thereon the clutch release arm 430 previously mentioned in connection with the article measuring mechanism. Thus at each downward movement of the reciprocable curved link 509 which carries the cutter carriage downward, the actuating lever 653 is pivoted in a clockwise movement about the pivot 655 from the upper-

most position shown in Fig. 4 to the lower position shown in Fig. 25. Thus the clutch actuating lever 291 is kicked outward by the cam member 434 and roller 432 to disengage the feed roll clutch just prior to the severing of the wrapping material by the cutter blades 622, 623 and 630.

The movement of the article carrier 500 with respect to that of the cutter carriage 600 is arranged so that just prior to the engagement of the marginal portions of the cutting blades at the commencement of a wrapping material severing operation, the article platform 501 engages the end of the adjusting bolt 642 to pivot the lever 637 in a counterclockwise direction as viewed in Fig. 6 so that the compensator bar 635 moves to the solid line position indicated in Figs. 7 and 17. This movement of the compensator bar 635 from the broken line position of Fig. 6 to the solid line position prior to and during the severing operation of the wrapping material serves to position the wrapping material adjacent the cutting edges of the knives in a substantially horizontal position so that a clean cut shearing action is obtained. Furthermore, this movement of the compensator bar tends to maintain a slight tension in the wrapping material during the severing so that the cutting is facilitated and the probability of wrapping material sliding between the cutting blades without being severed is minimized.

An additional feature of the compensator bar 30 is its capacity to withdraw a short length of wrapping material from between the carrier bar 301 and gripper bar 318. This is in effect a reverse movement of the wrapping material which has just been carried upwardly in the path of an article advancing to the carrier and occurs before the web is severed. Accordingly, by regulation of the amount of wrapping material thus withdrawn from the carrier bars the relative position of a sheet of wrapping material with respect to the article to be wrapped thereby may be regulated. This longitudinal adjustment of the wrapping material serves to position the edge of the sheet last fed with respect to the bottom of the article. In this manner the relative position of the overlapped portions of wrapping material underneath the article is adjusted with respect to the bottom of the article. It is usually desirable to have this bottom overlap centered longitudinally of the bottom of the article. Hence in the event that the overlap is altered by means of the adjusting thumb wheel 415 described in connection with the article measuring mechanism, it may be desirable to also adjust the amount of wrapping material withdrawn from the carrier bars by the compensator 635 to center the bottom lap. This adjustment of the compensator bar is accomplished by altering the position of the adjusting bolt 642. Movement of this bolt so that it is engaged at an earlier position of the carrier movement by the carrier platform 501 causes a greater pivotal movement of the crook lever 637 and a correspondingly greater movement of the compensator bar away from the cutters 622 and 623. The greater this movement of the compensator bar the greater is the amount of wrapping material withdrawn from the carrier bars, so that the last portion of wrapping material advanced by the feed rolls and which is folded upwardly against the bottom of the article upon movement of the latter onto the carrier has its edge advanced to the rear side of the article. Conversely, adjustment of the bolt 642 so that the movement of the compensator bar 635 is diminished, moves the edge of the wrapping

material first folded under the article away from the rear side of the article and advances the center line of the overlap toward the front side of the article.

Wrapping material smoothing plate

An article moving on the carrier 500 to the outfeed station of the wrapping machine passes adjacent a smoothing plate 700 (Figs. 2, 3, 5, 7, 16, 48, 49 and 51 through 54). This plate is suspended transversely of the wrapping machine above the infeed station and has upturned ends which form flanges 701 (Figs. 5, 7 and 16). These flanges are pivotally connected at 702 to ears 703, depending from the bottom edge and at the ends of a pivoted supporting plate 704. This supporting plate has its upper edge secured to a square bar 705 journaled in the side frames. One end of this bar extends beyond the side frame 5 and has secured thereon a lever 706 (Figs. 4 and 16), connected by a longitudinally adjustable link 707 (Figs. 5 and 7) to an actuating lever 708. This actuating lever is reciprocated in an arcuate path in a manner to be hereinafter described, so that the square bar 705 reciprocates the supporting plate 704 in an arcuate path.

An inwardly extending finger 709 (Fig. 16) on one of the flanges 701 is arranged to engage the supporting plate 704 to restrict the downward or counterclockwise pivotal movement of the smoothing plate 700 with respect to the supporting plate, as viewed in Figs. 5 and 7). A link 711 (Fig. 16) is pivotally secured at 710 to one of the flanges 701 and has an elongated longitudinal slot 712 (Fig. 9) at its opposite end slidingly carried on a bolt 713 (Fig. 13) secured in a downwardly extending bracket 714 fastened to the cross member 11.

When the article carrier 500 is at the infeed station of the wrapping machine the square bar 705 has been pivoted to move the supporting plate 704 and smoothing plate 700 to their lower limit of movement (see Fig. 7). In this position the smoothing plate is also at its limit of counterclockwise or downward pivotal movement with respect to the supporting plate 704, the smoothing plate finger 709 engaging the back of the supporting plate 704. Also, the bolt 713 is adjacent the end of the slot 712 nearest the pivot 710.

Upon upward movement of the carrier 500 to the outfeed station of the wrapping machine (see Fig. 5) the square bar 705 moves the plates 700 and 704 in a clockwise direction, so that, as an article on the carrier 500 passes these members, the pivots 702 are moved to a position substantially directly beneath the axis of the bar 705 and the plane of the supporting plate 704 is substantially vertical. During this movement of the supporting plate to the vertical position the link 711 slides on the bolt 713 until the latter reaches the end of the slot 712, at which time further sliding movement of the link on the bolt is arrested and the link merely pivots on the bolt 713. After the link 711 is thus arrested in its longitudinal movement, continued pivotal movement of the square bar 705 causes the link to move the smoothing plate 700 around the pivots 702 in a clockwise direction to a position in which the smoothing plate extends upwardly from the pivots 702, as shown in Fig. 53. During the clockwise pivotal movement of the square bar 705, in which the smoothing plate moves from the position shown in Fig. 7 to that shown in Fig. 5, an article has been elevated from the in-

feed station to the outfeed station by the carrier 500 and moves past the smoothing plate. During this movement the latter plate engages the wrapping material, first with its tip edge 715, and then with its flat surface, which moves over the top and down the rear side of the article. This action of the smoothing plate 700 is particularly efficacious in producing a smoothly wrapped package and will be later referred to in the description of the wrapping operation. As the article is completing its movements to the outfeed station the supporting plate 704 is held by the bar 705 in a position substantially parallel with the direction of relative movement of the article and the smoothing plate 700 is thus supported in a like position by the plate 704.

Top end folders

Movement of the carrier 500 to the outfeed station carries an article positioned thereon between a pair of top end folders which perform end folding operations on portions of wrapping material projecting over the ends of the advancing article. Each of these folders includes a top end folding member 716 (Fig. 37) and a top end fold starter 717. The top end folding member has a substantially flat article-engaging portion 718, and spaced parallel top and bottom portions 719 and 720, respectively. The portions 719 and 720 extend laterally from the flat article-engaging portion 718, so that the surface of the latter is unobstructed for intimate engagement with the end of an article. Top portion 719 is secured to a channel-shaped supporting member 722, which is secured to a hinge member 723. The hinge member is pivoted at 724 to a bracket 725. The top end fold starters 717 are each carried by spaced, parallel, vertically extending rods 726 having sliding engagement with bosses 727 formed in the top and bottom portions 719 and 720 of the top end folding member. By adjusting the position of lock nuts 728 on the rods 726, the distance which the top end fold starter 717 is suspended below the bottom portion 720 of the member 716 may be regulated.

Vertical edge 729 of the article-engaging portion 718 of each of the top end folding members does not extend rearwardly sufficiently far for the top end folding member to overlie the roller 511 carried by the platform 501. Accordingly, the portion of wrapping material extending past the ends of an article from the rear side thereof is not engaged by the end folding member 716 as the article is moved to the outfeed station of the wrapping machine.

The top end fold starter 717, which may suitably be in the form of a substantially flat plate is preferably shorter than the top end folding member, so that it has a rear edge 730 which does not extend as far toward the folding and sealing channel as does the vertical edge 729 of the top end folding member. As shown in Fig. 38, wrapping material folding edge 731 of the starter 717 is spaced outwardly from the plane of the article engaging surface of the portion 718 of the top end folding member. Thus the top end fold starter 717 is arranged to engage the portion of wrapping material projecting over the end of an article and commence the folding of this projecting portion downwardly against the end of the article as the latter is moved by the carrier 500 to the outfeed station. Since the folding edge 731 of the top end fold starter is spaced a greater distance away from the end of the article than the top end folding member, it serves

to gradually break the top end fold so that this fold may be completed without tearing or otherwise injuring the wrapping material. Because the rear edge 730 of the top end fold starter extends only a short distance beyond the center of the end of the article, as shown in Fig. 37, it promotes a progressive rolling action of the wrapping material during the formation of the top end fold. Accordingly, when the top end folding member 716 engages the wrapping material the top end fold starter 717 has performed advantageous preliminary operations on the wrapping material.

In Fig. 37 the portion of wrapping material projecting over the end of an article is engaged by the top end fold starter 717. This portion of the wrapping material is being folded downwardly against the article and a rolling action occurs between the portion of wrapping material engaged by the top end fold starter and the portion which extends from the rear side of the article. The distance between the top end fold starter 717 and the bottom portion 720 of the top end folding member 716 is preferably less than the length of the flap of wrapping material which forms the top end fold. Accordingly, the top end folding member engages this flap to hold it against the end of the article before the top end fold starter moves below the bottom edge of the flap. Moving past the first end folding member 525 on the outside thereof the top end fold starter engages wrapping material included in the bottom end flap and presses it against the platform 501 of the carrier (Fig. 39). This position is reached when the upper movement of the carrier brings the platform 501 into engagement with the top end fold starter and moves the latter upwardly, so that the rods 726 slide in the bosses 727 of the top end fold member.

A spacing member or pad 732, which may be suitably formed of rubber or leather, is secured at an end of the starter 717 opposite the rear edge 730. This pad is arranged so that a slight space is provided between the top end fold starter and the platform 501 of the carrier to accommodate the bottom flap of the wrapper. At the upper limit of movement of the carrier 500 the top end fold starter 717 is substantially in engagement with the bottom portion 720 of the top end folding member, as shown in Fig. 40. In this position the top end folding member is against the end of the article to hold the first end fold and top end fold in place, and the wrapping material extending from underneath the article is held against the platform 501 of the carrier by the top end fold starter 717.

Article advancing ram

Upon reaching the outfeed station an article is moved from the carrier 500 into a folding and heat sealing channel by a ram (Figs. 1, 5, 7, 16 and 31 through 34). This ram has an article engaging pusher 733 mounted on a support 734, secured on the end of the horizontally reciprocable bar 735. This bar is carried in elongated sleeves 736 and 737, which are formed on the cross member 7 and arranged so that the rod 735 is positioned longitudinally of the wrapping machine midway between the side frames 5 and 6. The bar is given a sliding movement by a link 738 pivoted to the support 734. The opposite end of the link is carried by arm 742 which reciprocates in an arcuate path and is secured on the reciprocated shaft 744, which extends transversely across the end of the machine and is

Journalled in upwardly extending portions 745 (Figs. 3 and 4) of the side frames 5 and 6. This shaft extends a short distance beyond each of the side frames and the end extending beyond the frame 5 has secured thereon the actuating lever 708, previously described in connection with the smoothing plate 700. The end of the shaft 744 extending beyond the side frame 6 has secured thereon the drive lever 746 (Fig. 3). This lever is connected by an adjustable length link 747 to the end of a crank lever 748 secured on the outside of frame 6 to main drive shaft 18 which rotates continuously during the operation of the machine. The drive lever 746 secured on the reciprocated shaft 744 is of greater length than the crank rotating lever 748, so that the amplitude of movement imparted to the link 747 by the rotating crank lever 748 is insufficient to move the lever 746 and shaft 744 through 180°.

The arcuate reciprocatory movements of the arm 742 move the ram back and forth over the outfeed station of the wrapping machine and into and out of the folding and sealing channel. Fig. 5 shows the mechanism with the pusher 733 in retracted position in readiness for an article advancing movement, and Fig. 7 shows the mechanism with the pusher 733 at its extreme article advancing position.

In moving an article from the carrier 500 into the folding and sealing channel, the pusher 733 passes between the first end folding members 525. Accordingly, in accommodating the packaging combination to articles of various lengths, pushers of different lengths are preferably employed, since it is desirable that the pusher extend across substantially the entire distance between the first end folding members to apply a uniform and firm pressure across the entire length of the front side of the article. Referring to Fig. 33, a central portion of the pusher 733 has formed thereon a dovetail holding element 749 which has sliding engagement in a vertically arranged T-slot 750 in the support 734. Accordingly, the pusher 733 is readily slidable into and out of the T-slot 750 for replacement by a different pusher having a suitable length. In addition, this vertically sliding arrangement of the pusher 733 is advantageous in the event that the operator inadvertently neglects to change the pusher when adjusting the wrapping machine to articles of shorter length. In such case the first end folding members 525 engage the bottom edge of the pusher 733 and slide the pusher vertically out of the T-slot 750 from the broken line position to the solid line position indicated in Fig. 34, thus avoiding injury to the machine.

Notches 751 extend upwardly from the bottom edge of the pusher 733 to receive the rods 517 and portions of the article-engaging face of the pusher 733 adjacent the notches 751 are removed to provide recesses 752, which accommodate the article-engaging plates 519. The recesses 752 are preferably of greater depth than the thickness of such plates, so that upon engagement of an article by the pusher 733 in advancing the article into the folding and sealing channel the article is disengaged from the plates 519. This permits downward movement of the plates upon the commencement of the return of the carrier to the infeed station without their having substantial frictional engagement with the article or wrapping material, thus facilitating the withdrawal of the plates without tearing or injuring the wrapping material.

A pair of brackets 753 extend upwardly and

rearwardly from the support 734 in spaced parallel relation, and, between their rearward ends, pivotally carry an article hold-down member 755 which extends forwardly over the pusher 733 (Fig. 32). This hold-down has a substantially flat article-engaging portion 756 positioned in front of the pusher and arranged to engage the top of articles elevated to the outfeed station by carrier 500. Forward marginal portions 757 of the article-engaging portion 756 are formed upwardly to avoid contact with the article-engaging plates 519 in the event that the carrier 500 moves to the outfeed station without an article.

The forward end of the hold-down member 755 is formed with an upwardly extending article-pushing portion 758. This portion has a substantially flat surface and is reinforced by a centrally positioned rib 759 which extends rearwardly thereof, and is secured to the article-engaging portion 756. At a central portion of the hold-down is formed an upstanding arm 760. The extremity of this arm receives a pin bolt 761 which has sliding engagement in an elongated slot 762 formed longitudinally in the end of a link 763. The other end of this link is pivotally carried by an extension 764 (Fig. 5) at the extremity of the arm 742.

Upon retraction of the pusher 733 and article hold-down 755 after the completion of an article-advancing movement, the link 763 is retracted by the arm 742, so that the pin 761 reaches its limit of movement in the slot 762 and the hold-down 755 is raised to the position indicated in Fig. 5. In this position the hold-down engages the top 35 of an article elevated by the carrier and may be slightly raised thereby, depending upon the particular size of the article. This raising of the hold-down is permitted by the movement of the pin bolt 761 in the slot 762. Upon an article advancing movement of the ram the arm 742 pivots in a clockwise direction, as viewed in Figs. 5 and 7, thus advancing the link 763 to the right. In the event that the hold-down 755 is resting on an article, the link 763 slides over the pin bolt 761 40 without effecting any movement of the hold-down, and upon retraction of the ram the hold-down merely slides off the rear of the article.

A bumper 765, suitably formed of rubber or other resilient material, is retained in an aperture formed in the hold-down 755 and arranged to engage a portion of the support 734 intermediate the brackets 753. This bumper absorbs the shock when the hold-down slides off the rear of an article, minimizing injury to the parts and promoting quiet operation. As an aid to the bumper 765 a spring 767 may be tensioned between the pin bolt 761 and the pivot bolt securing the link 763 in the extension 764. The tension of this spring is insufficient to independently sustain the weight of the hold-down 755 and effects a gentle lowering of the hold-down when the latter moves off the rear of an article.

To accommodate tall articles extensions 768 are formed on the pusher 733 as a continuation 65 of the article-engaging face thereof and are positioned with a space 769 between them so that they do not interfere with the movement of the hold-down 755.

Modified article hold-down

In Figs. 35 and 36 is illustrated a modification of the article hold-down arrangement for engaging the tops of articles at the outfeed station which may be supplemental to the article hold-down 755 previously described. Arms 770 extend

over the outfeed station of the machine and into the folding and sealing channel. At one end these arms have sleeves 772 disposed at right angles thereto and carried by pins 773 retained in brackets 774 secured to upstanding portions 775 of the cross member 7. If desired, a projecting flange 776 on the upstanding portion 775 may replace the brackets 539 to engage the pins 537 of the end fold starter lever arms 534. The pivot pins 773 are arranged with respect to the top surface of the flanges 776 so that the arms 770 rest on the latter and are positioned in a substantially horizontal position in parallel relation with one another. These arms may be positioned any suitable distance apart, preferably so that they will engage the tops of the articles as near the ends thereof as possible. Since they pivot downward between the top end folders 718 they must be close enough together so that the machine can be adjusted for the shortest articles to be packaged. The arms 770 are engaged by the top of an article elevated by the carrier 500 and pivot upwardly. At an intermediate portion 778 they curve downwardly to conform to the article top and seat snugly thereover providing a slight resistance to movement of the articles off the carrier. The portion of the arms 770 beyond the curves 778 have a hook effect on the article tending to rotate it in a counterclockwise direction as viewed in Fig. 36. In addition, the frictional engagement between the arms and the wrapping material on the top of the article increase the retarding effect. This feature of retarding the top of the article is advantageous in overcoming the tendency of the article to roll and unwrap which is caused by the frictional engagement of the wrapping material portion E between the rollers 511 and 550. At the initial movement of the article into the folding and sealing channel the retarding effect is most pronounced and diminishes as the movement is completed on account of the movement of the article from under the curved portion 778 and the upwardly curved end portions 779 of the arms which ride over the top of the article.

Folding and sealing channel

At the outfeed station is positioned the entrance to the folding and heat sealing channel, which includes a bottom folding and sealing plate 800 and spaced parallel side plates 801 (Figs. 1, 9, 13, 16 and 37). The bottom plate is arranged so that its article-receiving edge 802 is positioned transversely of the machine adjacent the level of the carrier 501 when the latter is at the outfeed station and with the roller 550 closely adjacent the edge 802. This plate is carried by cross members 11 and 12, extending between the side frames of the machine, and is provided with a plurality of ridges 803 extending transversely of the path of articles.

The ridges 803 slope gradually upward in the direction of article movement and from the crest of each rib there is an abrupt drop to the valley between ribs, permitting a relatively long, gradual incline to the crest of the next succeeding rib. The ribs thus have a stroking action on the wrapping material, effecting an efficient transfer of heat and promoting a tight seal of overlapped wrapping material. Heating elements 804 and 805 (Fig. 9) are secured against the bottom of the channel member 800 by holding plates 806 and 807, and heat losses by conductivity through the cross members 11 and 12 are minimized by 75

annular spacers 809 positioned about the holding bolts 810.

A thermostatic device 811 (Figs. 9 and 13) for regulating the electric current supplied to the heating elements, is carried in a depressed channel portion 812 formed in the holding plate 807 which supports the heating element 805. The side members 801 of the folding and sealing channel are suspended from a carrying member 814 adjustably secured to the top of the channel support 722 by bolts 815 passing through elongated openings 816 in the carrying member. The angularity of the side plates 801 can thus be adjusted with respect to one another and their distance apart adjusted with respect to the discharge or outfeed conveyor of the machine. Annular spacing elements 817 (Fig. 9) positioned about the bolts which secure the side plate members 801 to the carrying members 814 reduce heat losses. Heat guards 846 are suspended from the channel supporting member 722 in spaced relation with the side heater plates and are provided with insulating grommets 847 for the electric wires leading to the heating devices. A curved folding slot 819 extends upwardly from the bottom of the rear or folding edge 820 of each of the side plates. The portion of each of the side heating plates which first engages the end of an article may be maintained at an elevated temperature by a heating device represented at 821 and the portion of each of the side plates on the opposite side of the slot 819 is provided with a heating device indicated at 822. If desired these heating devices may be controlled by the regulating device 810 mentioned in connection with the bottom sealing plate. In order to improve the sealing action of side plates 801 the portions thereof above the folding slots 819 are provided with vertically extending ridges 823 formed on the side of the plates facing the folding channel. These ridges have a gradually rising slope on the side thereof which first engages the wrapping material and an abrupt drop away from the crest on the side thereof in the direction of movement of an article being advanced through the folding channel similarly to the ridges 803 of the bottom plate 800. The portions of the side plates which are beyond the folding slot 819 have ridges 824 formed therein by spaced grooves 825 (Fig. 9). These ridges are parallel with one another and extend in the direction of movement of articles through the folding and sealing channel so that heat may be intensely applied at spaced intervals to overlapped portions of wrapping material. The ends of the grooves 825 are open along the end of the side plates 801, from which the articles move into the discharge conveyor, in order that materials, such as wax and the like, used to seal the overlapped wrapper portions, will not accumulate therein.

The bottom of the folding slot 819 is defined by a surface 826 (Figs. 42 and 43) which slopes gradually upwardly in the direction of article movement from adjacent the article receiving edge 802 of the bottom heating plate 800. Preferably a thin-wedgelike leading edge 827 is formed on the side heater plate 801 at the end of the surface 826 (Figs. 37 and 39) and is arranged to be receivable between the ridges 803 of the bottom plate so as to be disposed below the crests of the ridges and avoid tearing wrapping material.

Preferably, the bottom surface 826 of the folding slot 819 is formed to progressively change from a substantially horizontal position at the

leading edge 821 to an angular position sloping steeply downward from the outside of the side plate to the inner side thereof and facing inwardly toward the folding channel.

The upper edge or margin of the folding slot 819 is defined by a relatively wide surface 829 (Fig. 42) which approximately parallels the surface 826. Accordingly, the flap of wrapping material projecting from beneath the end of an article and which is folded upwardly against the end of the article is engaged primarily by broad surfaces so that tearing of the wrapping material is minimized. The lowermost portion of the surface 829 is positioned substantially directly above the article receiving edge 802 of the bottom plate 800 and merges through a smooth curve into a leading or folding edge 820. This folding edge is extended upwardly and forwardly so that the upper portion thereof extends a considerable distance over the article receiving edge 802 and may even extend beyond the vertical edge 729 of the top end folding member 716 as shown in Fig. 37. For this reason the inner surface of each of the side plates 801 adjacent the folding edge 820 is outwardly beveled as indicated at 830, and adjusted by means of the bolts 815 and elongated openings 816 so that the portions of the side plates to first engage an article are further apart than the flat article engaging portions of the top end folding members and positioned on the outside thereof.

Since the folding edges 820 of the side sealing and folding plates 801 overhang the carrier 500 as the latter moves to the outfeed station, wrapping material projecting past the ends of an article carried thereon is engaged by the leading edges of the side plates before the carrier reaches its upper limit of movement.

Fig. 39 is a diagrammatic perspective view which shows the position of the parts substantially at the instant the top end fold starter 717 is engaged by the platform 501 of the carrier. The top end fold flap has been released by the top end fold starter but is held against the end of the article by the top end folding member 716. Interposed between this top end flap and the first end fold flap is the first end folder 525. The portion of wrapping material projecting from the rear side of the article has been engaged by the leading edge 820 of the side folding plate which has commenced to roll the wrapping material against the end of the article to form an end fold. This rolling movement continues as the carrier moves the article to the outfeed station and when the carrier is at its upper limit of movement as shown in Fig. 40 the folding operation performed by the side folding plate 801 is considerably advanced. As the article is moved into the folding channel by the pusher 733 the curved leading edges 820 of the side plates complete the formation of the folds and position the flaps of wrapping material previously projecting from the rear side of the article against the end thereof. Accordingly, this end folding operation is performed in two movements. In the first movement the end folding member or plate 801 moves in a direction from top to bottom of the article and the second movement is substantially at right angles to the first movement, the folding plate traveling from the rear side to the leading side of the article.

Bottom end fold creasers 835 are secured on pivot pins 836 journaled in apertures formed in the side plates 801 immediately above the lower end of the folding slot 819. The pivot pins

836 project through the side plates and have secured thereon hubs 837 (Figs. 37 and 39). A spoke 834 extending from each of the hubs has secured thereto a tension spring 838 carried by a boss 839 formed on the outside of the side plates 801. In this manner the creasers 835 are resiliently urged downwardly against the bottom plate 800. The creasers extend across each of the folding slots a short distance inwardly of the open end thereof and are arranged to engage a portion of wrapping material connecting the bottom flap and the portion folded against the end of the article by the folding edge 820 of the side plate, and crease such engaged portion along the bottom edge of the article. In the event that the formation of folds in the wrapping material preclude the formation of a crease by one of the creasers 835 along the bottom edge of the article, the creasers are carried upward in a counterclockwise rotational movement, as viewed in Fig. 37, to avoid tearing of the wrapping material. The article engaging surface of each of the side plates 801 adjacent the top surface 829 of the folding slot is recessed at 840 to accommodate the creasers so that the latter will not project into the path of articles moving through the folding and sealing channel.

A pair of article engaging arms 841 (Fig. 9) are pivoted at 842 at the extremity of extensions 843 formed on the side plate carrying members 814. These extensions are directed angularly upward so that the pivots 842 are positioned over the infeed station and above the top end folding members 716. Accordingly, the article engaging arms 841 are mounted for pivotal movement in a plane parallel with the direction of movement of the articles through the folding and sealing channel and adjacent the side plates 801. The extremities of the article engaging arms 841 have upwardly extending angularly disposed portions 844 and the downward pivotal movement of the arms is limited by pins 845 which engage the arms adjacent the pivots 842. As an article is moved from the carrier into the folding channel the top thereof adjacent the ends is engaged by the arms 841 which may be slightly elevated thereby and ride over the top of the article as the latter moves further into the folding channel. Upon movement of the article past the ends of the arms 841 the latter drop by gravity under the restraining influence of frictional engagement between the article and the angularly disposed portions 844 so that the arms are behind the article and the latter is prevented from retrogressive movement in the folding channel.

In moving an article into the folding and sealing channel from the carrier 500 the pusher 733 may not advance it far enough to complete the upward folding movement of the bottom end flap. Accordingly, the article comes to rest with the bottom end flap positioned in the folding slot 819 and remains in this position until the next article is moved into the folding channel. During this dwell the heated side plates 801 apply heat to both sides of the wrapping material which form the bottom end flap and portions of the side heater plates above the folding slot 819 apply heat directly to portions of wrapping material which will normally underlie the bottom end flap when the packaging is completed. Accordingly, these portions are rapidly and efficiently heated to effect a seal before the bottom end flap is brought into contact with the end of the article (see Fig. 42).

Discharge conveyor

Articles advanced through the folding and sealing channel are received on a discharge or cooling conveyor which serves to retain the overlapped wrapper portions in place until the seal becomes set or in the event that wax paper is used as a wrapping material until the heated wax is cooled. This conveyor (Figs. 1, 2, 3, 4, 9 and 13) comprises a bottom belt 850 and spaced parallel side belts 851. The bottom belt moves over the central portion of an article supporting apron 852 which is recessed to receive the belt 850 so that the top of the belt is substantially level with the surface of the apron. Cross members 853 (Figs. 9 and 13) support the apron 852 and are carried between longitudinally extending framing members 854. These members are supported at the end of the discharge conveyor adjacent the folding and sealing channel by a shaft 855 which is journaled in brackets 856 secured to the side frames 5 and 6. At the slicing machine end of the discharge conveyor the framing members 854 are carried on an upstanding portion of brackets 857 (Fig. 2) which are secured to the side frames 3 of the slicing machine 2.

The bottom belt 850 is endless and is carried on a roller 858 (Figs. 9 and 13) secured on the shaft 855 and a similar roller rotatably mounted on a shaft 859 (Fig. 1) extending between the framing members 854 at the opposite end of the apron 852. Riding on the shaft 855 on each side of the roller 858 are brackets 860 (Figs. 9 and 13). These brackets are longitudinally slidable on the shaft and have upstanding spindles 861 threadedly secured therein. Each of these spindles carries a vertically disposed roller 862 upon which the side belts 851 of the discharge conveyor are carried. At the opposite end of the conveyor the endless side conveyor belts are carried by a similar set of spindles and rollers 863 and 864 respectively (Figs. 1 and 2) which are likewise slidably carried on the shaft 859. Positioned above the rollers 862 and 864 which carry the endless side belts are longitudinally extending supporting members 866 carried on the extremities of the spindles 861 and 863. A plurality of spaced parallel reinforcing members 867 (Fig. 9) are suspended by brackets 868 from the supporting members 866 between the two laps of each of the endless side belts 861 and arranged to prevent substantial deflection of the article engaging lap of the belts throughout substantially the entire length of the conveyor.

The belts 850 and 851 may be suitably formed of a flexible material such as canvas. In order to tension the belts idling rollers are provided, (Figs. 13 and 15). The idlers for the bottom belt 850 comprise a pair of rollers 870 and 871 mounted on spindles 872 arranged in spaced parallel relation between rocker arms 873. Each of the rocker arms 873 is centrally apertured to receive a bar 874 which is secured therein and extends to a bracket 875 secured on the under side of one of the frame members 854. By means of tightening bolts 876 (Figs. 3 and 4) brackets 875 are arranged to clamp the bars 874 in various positions so that the bottom lap of the belt 850 can be directed in a sinuous path between the rollers 870 and 871. Circumferential flanges 877 at the marginal portions of the rollers 870 and 871 prevent the belt from riding over the ends of the rollers and maintain the belt in alignment thereon.

The side belts 851 each have their outer lap directed in a sinuous path by a pair of idling rollers 880 and 881. These rollers are carried on spaced parallel, vertically arranged spindles 882 which are secured in the extremities of a rocker arm 883. Secured in a central portion of the rocker arm is a stub shaft 884 adjustably carried in a split journal supporting bracket 885. This journal is secured on the top of the supporting members 866 so that the idling rollers are suspended therefrom and by clamping the stub shaft 884 in various positions the tension in each of the side belts can be individually regulated. During operation of the machine the bottom belt 850 and side belts 851 are moved in synchronous timed relation with one another so that they cooperatively engage the bottom and ends of articles moving out of the folding and sealing channel and carry them in the direction of the slicing machine. The bottom belt 850 is driven by the roller 858 secured on the shaft 855, the latter being driven by sprocket 887 secured on an end portion of the shaft which extends beyond the journal bracket 856 on the side frame 5 (Figs. 4 and 13). A chain belt 888 forms a driving connection between a small sprocket 889 secured on driving shaft 15 and the sprocket 887 such that the discharge conveyor carries articles away from the sealing channel in substantially side-by-side relation.

Side belts 851 are driven by the rollers 862 each of which has a bevel gear (not shown) secured on its bottom end meshing with a bevel gear 890 (Fig. 11) driven by the shaft 855 and arranged for longitudinal sliding engagement therewith. The gear 890 is secured on a sleeve 891 having longitudinal sliding engagement with the shaft 855 and keyed thereto so as to have a driving connection regardless of the relative longitudinal position of the sleeve 891 with respect to the shaft. The brackets 860 are carried on the sleeves 891 so that the latter are freely rotatable therein. Collars 892 threadedly engage ends of the sleeves 891 which extend beyond the brackets 860 from the side of each thereof opposite the bevel gears 890 and retain the sleeves within the brackets 860 so that the sleeves and brackets move along the shaft 855 together.

At the end of the discharge conveyor removed from the wrapping machine, articles are received by a platform 893. This platform is supported in cantilever fashion by a cross bar 894 carried between the ends of extensions 895 of the brackets 857. The receiving end 896 is anchored at the end of the discharge conveyor in any suitable manner such as by means of pins (not shown) engageable under one of the flanges of the longitudinal framing members 854. Thus articles may be fed into the packaging combination and after being automatically sliced and wrapped are returned to an outfeed or loading platform positioned directly above the infeed conveyor so that if desired the mechanism can be operated by one person with resultant economy and efficiency.

Article guides and adjustment

As previously mentioned the brackets 860 are longitudinally slidable on shaft 855 and accordingly may be moved toward and away from one another to vary the distance between the side belts 851 thus accommodating the discharge conveyor to articles of different widths. Extensions 896 (Fig. 11) on the brackets 860 are apertured 75 to receive threaded sleeves 891. These sleeves

engage oppositely threaded ends of an adjusting shaft 902 (Figs. 9 and 13). The sleeves 901 are retained in the apertures of the extensions 900 and secured against rotation by bolts threaded in the extensions 900 and receivable in one of a plurality of radial holes formed in the sleeves 901. By rotation of one of the sleeves 901 on the shaft 902 with respect to the bracket 860 individual longitudinal adjustment may be made.

The ends of this shaft are journaled in bearing members 903 secured in the channel of the longitudinal framing members 854. If desired the bearing members 903 may also be arranged to serve as journals for the shaft 855 as shown. The adjusting shaft 902 is secured against longitudinal movement by a circumferential collar 904 received on a reduced diameter portion 905 of the shaft and bearing against the bearing member 903. The reduced diameter portion of the shaft 902 extends beyond the framing member 854 on the operator's side of the machine and has secured thereon a hand wheel 906. Sleeve 907 at the hub of the wheel receives the shaft 902 and cooperates with the collar 904 to prevent longitudinal movement of the adjusting shaft.

A chain belt 909 carried on a sprocket 910 secured on adjusting shaft 902 imparts a rotational movement to an adjusting shaft 911 (Fig. 1) at the opposite end of the discharge conveyor by means of a sprocket 912. The adjusting shaft 911 is arranged to move the rollers 864 toward and away from one another similarly to the manner in which the shaft 902 moves the rollers 862. However, the rotation of the adjusting shaft 911 is controlled by the chain belt 909 so that the two adjusting shafts are rotated in synchronous fashion thus simultaneously moving both ends of the discharge conveyor side belts 851 toward and away from one another so that they are maintained in parallel spaced relation. On account of the oppositely threaded ends of the adjusting shafts and the latter being individually secured against longitudinal movement the side belts 851 are each maintained the same distance from the bottom belt 850 so that the latter is positioned centrally between the side belts.

The brackets 725 which pivotally carry the top end folders and side members of the folding and sealing channel, are carried on the supporting members 866. In this manner the side members of the heat sealing channel and the end folding members are synchronously moved with the side belts 851 of the discharge conveyor. The securing bolts for the brackets 725, including the spindles 861, pass through elongated openings 914 in the brackets to permit slight longitudinal adjustment.

Supporting the top end folders 717 and side plates 801 on common pivots enables them to be raised by an article which, on account of the machine being out of adjustment or the article misplaced on the carrier, engages the underside of the end folders (see the broken line position indicated in Fig. 37). This pivotal movement is a safety feature minimizing injury to both the machine and the article, avoiding crushing of the latter and straining of the former. The folders and side plates are retained in position during normal folding operations solely by their weight which is insufficient to cause injury to the mechanism in the event of engagement between misadjusted parts. Location of the pivots 724 adjacent the sides of the outfeed conveyor enables the pivotal movement of the folders and side plates to occur in planes parallel with the

relative movement of the articles past these members and parallel with the direction of movement of articles through the folding and sealing channel. In cleaning the sealing plates, the side plates can be elevated away from the bottom plate without interfering with the adjustment of the machine and without loosening or removing any parts.

Article guides 915 are positioned in spaced parallel relation over the infeed conveyor apron 110 to engage the ends of articles moving over the infeed conveyor to the wrapping mechanism. These guides may be formed of channel members having the channels facing outwardly so that the flat web portion is engageable with the ends of the articles. Adjacent the infeed station the guides are suspended by bars 916 rigidly secured in extensions 917 of the brackets 860 carried on the shaft 855. In a similar manner the ends of the article guides 915 adjacent the discharge plate of the slicing machine are rigidly suspended by bars 918 (Fig. 2) carried on brackets supporting the rollers 864 on the shaft 859 and which correspond to the brackets 860. Since, as previously mentioned, the hand wheel 906 simultaneously moves both ends of the side belts 851 to maintain the belts in parallel relation, the bars 916 and 918 are also moved in synchronization with the movement of the conveyor belts to maintain the guides 915 in parallel relation. The arrangement of the bars 916 and 918 is such that the distance between the guides 915 is equal to the distance between the side belts 851 so that both the infeed conveyor and outfeed conveyor are automatically and simultaneously maintained in adjustment to receive articles of the same length.

Rotation of the adjusting hand wheel 906 moving the side belts 851 toward and away from one another is in this manner arranged to simultaneously adjust the article guides 915 of the infeed conveyor together with the top end folding members and side plates of the folding and sealing channel. Accordingly, all of the wrapping machine parts which need be adjusted to accommodate articles of different lengths are automatically moved in synchronization by the single wheel 906 with the exception of the first end folding members 525 which are regulated by the knurled hand wheel 528.

Desirably the guide 915 adjacent the loading tray apron 130 is removable so that it will not obstruct the feed of unsliced articles onto the infeed conveyor. One manner of providing for removal of the article guide is illustrated in Figs. 9 and 12 in which the guide is severed and a tongue element 920 is secured in the channel of one portion. This tongue element extends into the channel of the adjacent portion of the severed guide and is retained therein by a pin 921 extending vertically through the tongue element 920 and receivable in slots 922 formed in the top and bottom flanges of the adjacent article guide. By slight longitudinal movement of the severed guides away from one another the pins 921 may be disengaged from the slots 922 and a portion of the article guide removed.

Drive

The wrapping machine drive motor 4 is suspended from a carriage 20 (Fig. 28) slidably supported on rods 21 carried in bosses 22 formed on the cross member 8. An adjusting shaft 23, positioned parallel with and between the rods 21, extends through the cross member 8 at the rear

end of the machine and is rotatably mounted therein and secured against longitudinal movement. This shaft threadedly engages the carriage 20 and upon being rotated by a hand crank secured on the portion which extends from the rear of the machine is arranged to slide the motor carriage 20 back and forth on the bars 21. A V-belt 26, driven by the spring pressed split pulley 25 secured on the motor drive shaft, rotates the relatively large pulley wheel 27 which is carried exteriorly of the machine on stub shaft 28 journaled in the side frame 5. Movement of the motor carriage 20 back and forth on the bars 21 varies the speed of the mechanism by changing the effective diameter of the split pulley 25.

A pinion 30 secure on the end of the stub shaft 28 opposite the pulley wheel 27 meshes with and rotates main drive gear 31 (Fig. 29) which is rotatably mounted on the main drive shaft 18, previously mentioned in connection with the ram and article hold down. The hub 32 of the main drive gear 31 has secured thereon a clutch drum 33 having an internally directed cylindrical clutch face 34 concentric with the axis of the drive shaft 18. A clutch spider 35 is keyed to the main shaft 18 within the clutch drum 33 and carries a pair of clutch shoes 36 (Fig. 30). These shoes are pivoted at 37 on extremities of the spider 35 closely adjacent the friction face 34 of the clutch drum.

Clutch actuating levers 39 are pivoted for movement in a plane passing through the axis of the main drive shaft 18, on spaced parallel pins 40. These pins are secured in the spider 35 on opposite sides of the shaft 18. A cone 41 having its axis concentric with the axis of the main drive shaft is rotatably and slidably carried by the latter and has its narrow end directed toward the clutch spider 35. Upon movement of the cone 41 toward the spider, rollers 42 adjustably carried at the ends of clutch levers 39 ride up the inclined surface of the cone to spread the levers 39. Toggle pins 43, having rounded ends seated in sockets of the lever arms 39 adjacent the pivot pins 40, have round headed adjusting nuts on their outer ends engageable in sockets within the clutch shoes 36. In this manner movement of the cone 41 between the rollers 42 forces the clutch shoes 36 (which may be faced with a suitable lining such as asbestos or hard rubber) into engagement with the friction face 34 of the clutch drum 33 to establish a driving connection between the main drive gear 31 and the main drive shaft 18.

Tension springs 44, extending between pins secured in the clutch shoes and the spider 35, are arranged to pivot the shoes out of engagement with the friction face 34 upon withdrawal of the cone 41 from between the rollers 42. The cone terminates in a cylindrical portion 45 upon which the rollers 42 rest when the clutch parts are in driving engagement.

The rollers 42 and toggle pins 43 are adjusted so that upon engagement of the clutch the friction between the shoes and drum is just sufficient to transmit the power required to operate the mechanism. Accordingly a safety feature is provided since the clutch slips if an article gets caught in the mechanism, permitting non-injurious arresting of movement of the wrapping machine parts while the motor runs and the clutch is engaged.

An annular channel 46 (Fig. 28) is formed at one end of the cylindrical portion 45 of the cone 75

41 and receives bearing elements carried on the ends of pin bolts 47 which are secured in the ends of a sliding yoke 48 carried on the shaft 18. An arm 49 extends laterally from the yoke 48 and has a bifurcated end received on the oscillating drive shaft 17 to prevent rotation of the yoke. In engaging and disengaging the clutch in starting and stopping the mechanism the yoke 48 is moved longitudinally on the shaft 18 by an adjustable length link 51 extending to a crank lever 52 at the lower end of a vertical rod 53 (Fig. 3) mounted on the outside of the side frame 6. This rod is rotatably mounted in brackets and at its upper end has a hand lever 54. 5 An adjustable length tie rod 56 (Figs. 1, 2 and 3) extends horizontally between a lever 57 secured on an intermediate portion of the rod 53, and a lever 58 secured on a vertically positioned rod 59 rotatably mounted in brackets on the side frame of the slicing machine. By means of a handle 60 secured on the rod 59 the clutch mechanism just described, which controls the entire wrapping and conveyor mechanism, may be controlled from adjacent the slicing machine to facilitate one man operation of the packaging combination.

Secured on the main drive shaft 18 adjacent the side frame 6 is a sprocket 62 (Fig. 28) which, by means of a chain belt 63, drives a sprocket secured on the driving shaft 13 (Fig. 9). On the end of the shaft 13 adjacent the side frame 5 is a gear 65 which meshes with a gear 66 secured on the driving shaft 15, thus actuating the latter in timed relation with the driving shaft 13 and the main drive shaft 18, but in a reverse direction.

As previously mentioned, the infeed conveyor is driven from the driving shaft 13 by the chain belt 123 and the outfeed conveyor is driven from the driving shaft 15 by the chain belt 888. Accordingly, the gears 65 and 66 synchronize the operation of the infeed and outfeed conveyors of the machine with each other and with the main driving shaft 18. Preferably, the infeed conveyor of the slicing machine is also driven by a chain belt 67 carried on a sprocket 68 secured to the infeed conveyor driving shaft 13. Thus all of the conveyors of the packaging combination are positively driven in synchronized timed relation with one another and with the wrapping mechanism.

Referring to Figs. 4, 28 and 63, a rotating driving crank 70 secured on the main drive shaft 18 outside the frame 5 drives a sector 71 secured on the end of the oscillating drive shaft 17 in a pivotal movement by means of a driving link 72. The radius of movement of the pivot for the driving link 72 carried on the sector 71 is greater than the radius of the driving crank 70. In this manner the rotational movement of the shaft 18 is converted into oscillatory movement of the shaft 17 in synchronization therewith so that one oscillation of the shaft 17 occurs for each revolution of the main driving shaft 18. The periphery of the sector 71 is toothed to engage and drive a gear 73 secured on oscillating drive shaft 16, previously mentioned in connection with the carrier and clamping bars 300, 301, and 318, carrier 500 and cutter carriage 600. This gear connection insures synchronous oscillatory movements of the shafts 16 and 17 so that the cam lever 327 for separating the clamping bar 318 and carrier bar 301 is operated in synchronous relation with the movement of the carrier bars, the former being actuated by the driving lever

326 carried externally of the side frame 6 on the oscillating shaft 17 and the latter being actuated by lever arm 307 secured between the side frames on the shaft 16. In addition, the carrier 500 and cutter carriage 600 are synchronously actuated with the remainder of the mechanism by the crank levers 508 secured on the oscillating shaft 16.

Previous reference has been made to the dia-grammatic illustration (Fig. 63) in connection with the movement of the article carrier 500. The gear 73 is oscillated through more than 180° by a materially smaller oscillation of the sector 71 on account of the radius of the sector being considerably greater than the radius of the gear 73. In addition to the dwell afforded the carrier at each limit of movement by the relatively small longitudinal travel of the curved links 509 adjacent dead center positions of the cranks 508 an additional dwell is provided by the relatively small longitudinal movement of the driving link 72 as the rotating drive lever 10 (Fig. 4) (secured on rotating main drive shaft 18) passes dead center positions. This dead center dwell of the link 72 effects a dwell at each limit of movement in the oscillation of sector 71 and shaft 17 which is cumulative to the dwell of the cranks 508 and the links 509.

The prolonged dwell of the carrier bars and clamping bar in their uppermost position, afforded by the dwell of the shaft 16, (which reciprobrates the bars through the lever 307 and the L-shaped link 306) permits the driving lever 326 oscillated by the reciprocating shaft 17 to carry the cam lever 327 into engagement with the clamping bar arms 311. Thus the cam levers 327 may be said to overtake the clamping bar arms 311 adjacent their respective limits of upper movement. Similarly the accumulative dwell afforded the movement of the carrier bar arms 302 on account of being actuated by the oscillating shaft 16 affords opportunity for the cam lever 327 to be moved out of engagement with the clamping bar arm 311 prior to the downward movement of the carrier bars and clamping bar.

In the driving arrangement described, cranks and levers have been advantageously combined and coordinated to provide, without the use of intricate cams, an actuating mechanism comprising a plurality of reciprocating, oscillatory and rotational movements, thus providing an economical construction which is smooth and quiet in operation. By the use of progressive driving in a plurality of oscillating shafts, some of the movements have been arranged to overtake others during dwell periods.

A tension spring 75 extends between cross member 8 and a chain 76 which rides on a sprocket 77 secured to the oscillating shaft 16. This spring balances the weight of the carrier and cutter carriage so that the operation of the mechanism is smooth and regular. Similarly, tension spring 79 (Fig. 3) secured at one end to a bracket plate 80 (Fig. 28) carried by and ex-tending inwardly from cross member 9, and at the opposite end to a chain 81 which is carried on a sprocket (not shown) secured on the shaft 303, balances the weight of the pivoted arms 302 and clamping bar arms 311. The chain 81 carried around the sprocket on the shaft 303 is secured thereto so that upon oscillation of the shaft 303 the chain winds and unwinds on the sprocket. A large hand wheel 83, which may also serve as a flywheel to dampen uneven or surging movement of the driving mechanism, is

secured on a portion of the driving shaft 15 which extends beyond the side frame 6. Upon disengagement of the main clutch by the hand lever 54 or the lever 60 the mechanism may be actuated by hand independently of the motor 4 and pulley wheel 27. This feature is of ad-vantage in adjusting the parts in setting up the machine.

Operation

In the preceding description of the wrapping machine combination the several parts have been treated independently in order that the construction and operation of each might be set forth with the greatest clearness. However, the machine operates as a unitary mechanism and all of the parts and movements function simultane-ously and in synchronous relation so that each may be said to contribute to the result produced by the whole. So that this cooperative relation of the various elements may be more clearly un-derstood, a description of the operation of the machine combination during the passage of an article therethrough is now made.

With the machine at rest, switches 85 and 86 (Fig. 3) mounted in switch boxes carried on the side frame 5 of the wrapping machine are thrown to start the motor 4 and close the electrical cir-cuits for the heating elements 804, 805, 821 and 822. Article guides 88 (Fig. 2) of the slicing machine infeed conveyor are adjusted to accom-modate articles of the length to be packaged and the adjusting hand wheel 906 rotated to simu-laneously adjust the wrapping machine infeed conveyor article guides 915, top end folders 716, side plates 801 of the folding and sealing chan-nel, and side belts 851 of the discharge conveyor, for the same sizes of article. A pusher 733 of suitable length is placed in the T-slot 750 of the ram and the first end folding members 525 on the carrier are adjusted for the particular article length by the hand wheel 528. A driving connection is established between the motor 4 and the conveyors and wrapping machine mech-anism by either of the main clutch hand levers 54 or 60. Articles are then placed on the infeed conveyor 14 (Fig. 2) of the slicing machine (after starting the slicing mechanism) or the infeed conveyor apron 110 of the wrapping machine, according to whether the articles are to be pack-aged sliced or unsliced.

An article being advanced over the infeed con-veyor apron 110 by one of the flights 113 en-gages the fingers 400 of the article measuring mechanism and causes the latch lever 425 to be released by the quadrant 405 (Fig. 19) permitting the compression spring 418 to move the clutch actuating arm 291 outwardly (Fig. 18), thus en-gaging the clutch elements 284 and 285 and estab-lishing a driving connection between the driving shaft 15 and feed rolls 221 and 228. These feed rolls (Fig. 44) instantaneously commence the feeding of the web W over the bed knife 630 and into a suspended position over the carrier bars 300 and 301.

This demand for wrapping material draws the slack roller 225 downward against the tensional resistance of the spring 242. Accordingly, the tension in the web W is increased and the corre-spondingly increased frictional engagement be-tween the constantly rotating booster roll 217 and the web W draws wrapping material from the rolls R. The operator, by watching the move-ment of the long arms 237 of the bell crank levers, can regulate the frictional engagement

between the collets 201 in the wrapping material rolls and the cone sockets 202 so that at each feeding of a sheet of wrapping material the slack roller 225 reciprocates in the path of maximum length.

During the feeding of the web W by the feed rolls 227 and 228 the carrier bars 300 and 301 commence their upward movement, engaging the under side of the web and carrying it upwardly past the end of the infeed conveyor of the wrapping machine in the path of an article advancing to the infeed station. Upon movement of the carrier bar 301 above the level of the infeed conveyor apron 110, the clamer or gripper bar 318, which has meanwhile been positioned as shown in Fig. 44, engages the opposite side of the wrapping material (Fig. 45) and moves upward in an arcuate path, carried by the bar 301. This movement of the carrier and clamping bars to pull the web W up in front and over the top of the article occurs while the article carrier 500 and cutter carriage 600 are descending and while they are removed from the infeed station. The engagement of the wrapping material web W by the carrier bar 301 and gripper bar 318 is sufficient to maintain the web taut as it is advanced by the feed rollers, but with insufficient force to advance the wrapping material independently of the feed rollers. Accordingly, the web W is not advanced after the feed rollers stop, nor faster than they operate to advance the web and the web slips between the carrier bar 301 and gripper bar 318 when the bars move faster than the web is advanced by the feed rollers and when the feed rollers stop. For a portion of their travel, the carrier and gripper bars move faster than the web is advanced by the feed rollers so that there is a slipping of the web between the carrier bar and gripper bar. Thus a portion E (Fig. 45) of wrapping material which is draped over the carrier bar 300 may progressively diminish as the carrier bars move to their upper position. For exceptionally small articles the wrapping material web may even be withdrawn completely from the upper carrier bar 300 so that in its draped position only the bottom bar 301 carries it. Thus the upper carrier bar 300 is particularly advantageous for very large articles since it serves to support the leading end of the wrapping material so that the latter does not hang downwardly far enough to be objectionably engaged by the article advancing to the infeed station, but is held in a draped position over the article. At their lower limit of movement the carrier bars are positioned substantially one above the other and the engagement of an under side of the web to carry it upward occurs first by the bar 300. During the upward pivotal movement the lower bar 301 follows substantially in the arcuate path described by the upper bar 300. In the accompanying drawings the web W has been shown in the approximate positions it would assume if the mechanism were stationary at the successive stages illustrated. In commercial operation of the machine the position of the web might be different, caused, for example, by the resistance to movement of the web through the air. The movement of the carrier bars through a common path enables the web to take a streamlined form, with the portion E trailing the bar 300 in parallel relation with the portion extending between the two carrier bars.

During the dwell of the bars at their upper limit of movement, the air pressure holding the wrapping material in streamlined form is re-

lieved and the web portion E moves to the position shown in Figs. 47 and 48. The carrier bars are no longer one above the other, but positioned to suspend the web over the top of an article 5 with the last portion of web advanced by the feed rolls across the front side of the article.

As the carrier bars approach their upper limit of movement the carrier 500 and cutter carriage 600 approach their lower limit of movement and 10 the compensator bar 635 engages the wrapping material to move it away from the upper cutters 622 and 623 (Fig. 46). This movement of the compensator bar tensions the wrapping material and may withdraw an additional amount from between the carrier bar 301 and gripper bar 318. Before the cutters commence severing the web W the movement of the clutch actuating lever 291 caused by the clutch release arm 430 disengages the clutch elements 284 and 285 and stops the 15 feed rolls 227 and 228, the brake 455 engaging the hand wheel 270. The web W, positioned horizontally over the bed knife 630 and held taut by the compensator bar 635, is then severed. The cam levers 327 engage the clamping bar arms 311 20 so that the web W is released by the clamping bar 318 and held against the carrier bar 301 by the soft tired wheel 514 which engages the lower carrier bar just prior to the release of the web by the clamping bar. Meanwhile the article A which 25 caused the feeding of this particular sheet of wrapping material has moved to the end of the infeed conveyor apron 110 and is positioned underneath the wrapping material suspended over the top and down the front side thereof (Fig. 48). The carrier 500 is now at the infeed 30 station at its lower limit of movement and the flight 113 which has been advancing the article A moves the latter onto the carrier platform 501 over the roller 511 which thus folds the portion 35 H (Fig. 49) of wrapping material last fed by the feed rollers upwardly against the bottom of the 40 article.

This movement of the article onto the carrier withdraws a portion of the wrapping material 45 yieldingly held between the carrier bar 301 and wheel 514. The amount of wrapping material thus withdrawn by the article is usually sufficient to cause the portion E to become disengaged from the upper carrier bar 300 (Fig. 49).

In addition to folding the last feed portion H of wrapping material against the bottom of the article the movement onto the carrier performs a first end folding operation. The wrapping material guides 536 of the end fold starters 535 55 (Fig. 50) engage portions K of wrapping material projecting from the front side of the article and break a fold therein so that the first end folding members 525 do not tear or injure the wrapping material in completing the first end fold.

The movement of the article onto the carrier is guided by the plates 519 which engage the wrapping material and hold the latter against the front side of the article and move with the 60 article, carrying rods 517 sliding in the sleeves 516. Upon release of the flight 113 by the track 119 so that the former is ineffective to further advance the article onto the carrier, the article A has been only incompletely moved onto the carrier and the latter commences its upward movement to the outfeed station of the machine. The cam levers 327 release the clamping bar arms 311 (Fig. 51) and the clamping bar 318 and carrier bar 301 again grip the wrapping material adjacent the end thereof which was first

advanced by the feed rollers. Simultaneously with the elevating of the article by the carrier the arms 311 and 302 oscillate downward, carrying the bars 301 and 318 in an arcuate path past the rear side of the article. This movement draws web W, held between the bars, down the rear side of the article so that it is suspended therefrom with the portion E first advanced by the feed rolls hanging below the platform of the carrier. Meanwhile the leading or tip edge 715 of the smoothing plate 700 has had a line engagement with the wrapping material longitudinally of the article so that the wrapper is "broken" over the top. The smoothing plate guides this "break" across the length of the article and smooths the wrapping material over the top and top rear corner of the article (see Figs. 51 and 52). As the smoothing plate moves over the top rear corner of the article the pivotal movement of the supporting plate 704 moving to its vertical position presses the smoothing plate against the rear side of the article to move the latter completely onto the carrier as shown in Fig. 53. Continued movement of the article past the smoothing plate 700 which is thus held in a substantially vertical position strokes the wrapping material downward over the rear side of the article, eliminating wrinkles and making a smooth package. In the event that it is a sliced article, such as a baked loaf, this action of the smoothing plate tends to straighten any slices which may be misplaced and move them into proper position.

Approaching the outfeed station, the end fold starters 535 are pivoted outwardly away from the ends of the article (Fig. 55) and the top end fold starters 717 engage portions L (Figs. 37 and 38) of wrapping material extending beyond the ends of the article at the top thereof, folding them downward against the ends of the article to form top end flaps. Meanwhile the carrier bars have moved below the level of the infeed conveyor apron and the gripper bar 318 is positioned above the plane of wrapping material feed in readiness for wrapping material to be advanced by the feed rollers upon actuation of the measuring mechanism by the next article.

As the carrier reaches its upper limit of movement the wrapping material M (Figs. 37, 39 and 40) extending between the portion H which protrudes from the bottom of the article at the end thereof and the first end flap K is creased along the bottom edge of the article by the top end fold starter 717 in cooperation with the carrier platform 501. The end fold starter also moves upwardly against the bottom of the top end folders 716 which meanwhile complete the top end folding operation.

The folding edges 820 of the side plates 801 engage the tops of the portions N (Figs. 39) of wrapping material extending from the rear side of the article as the carrier reaches the outfeed station and commence to roll these portions against the ends of the article. This operation is well advanced before the pusher 733 moves the article into the folding channel to complete the rear or second end fold.

The article hold-down 755 has engaged the top of the article (Fig. 56) to hold it on the carrier and prevent the rolling as the article is moved from the carrier into the folding and sealing channel. As the pusher 733 moves the article into the folding and sealing channel the depending portion of wrapping material E (Fig. 56), which was the first portion advanced by

5 the feed rolls, is engaged between the carrier roller 511 and roller 550 at the outfeed station, the latter being under the pressure of the spring pressed roller 551. This spring pressure can be adjusted during the operation of the wrapping machine by movement of the lever 564 (Fig. 13) so that the central portion of the wrapping material midway between the edges is engaged by the rollers 511 and 550 with sufficient friction to draw the wrapping material around the article to produce the desired tightness of wrap. Since the central portions of the rollers engage the wrapping material with the greatest force the rollers are rotated as the wrapper is withdrawn because of the direct pull effected by the bulk of the article. Accordingly, the edge portions of wrapping material which project beyond the ends of the article are fed by the end portions of the rollers 511 and 550 and the portion of wrapping material E is folded upwardly against the bottom of the article without wrinkles or creases (Fig. 58).

20 Pusher 733 disengages the plates 519 from the front side of the article, these plates being received in the recesses 752 formed in the article 25 engaging surface of the pusher 733. Accordingly, upon commencement of the downward movement of the carrier 500 (Fig. 59) which takes place before the article is completely received by the bottom plate 800 of the channel, there is a minimum dragging or scraping action between the plates 519 and the front side of the article. Upon the pusher 733 reaching its limit of article advancing movement, the arms 841, which have been riding on the top ends of the article, drop downwardly and the upstanding portions 844 thereof engage the front side of the article at the ends (Fig. 61) and prevent the article moving backwards in the channel on account of the resiliency of the articles being packaged.

30 The initial movement of the article into the channel may not carry the bottom end flap completely against the end of the article and it remains positioned in the folding slot 819 to absorb 35 heat from the side plates 801 until moved further into the channel by the next article or the pusher. The next article moved into the folding and sealing channel by the pusher 733 advances the article one article space in the channel and this 40 progressive movement continues until the articles 45 are received one by one in the discharge conveyor 50 channel formed by the side belts 851 and bottom belt 850, which hold the overlapped wrapper portions in position until the seal is completed.

50 It is disadvantageous to permit an article to remain in the sealing channel an excessive length of time due to the possibility of the heat injuring either the article or wrapper or both. Upon failure of an article to be elevated to the outfeed 55 station by the carrier the article hold-down 755 is not raised above the tops of the preceding articles and forward movement of the vertically arranged pusher 758 of the hold-down which is carried in advance of the pusher 733 engages the front side of the last article positioned in the sealing channel and moves it onto the discharge conveyor (Fig. 62).

60 During the elevation of an article from the infeed station to the outfeed station the ram is retracted across the infeed station out of the path 65 of the article and in readiness for an article advancing movement and the next article advancing over the infeed conveyor engages the fingers 70 400 of the measuring mechanism so that a sheet 75 of wrapping material is advanced by the feed roll-

ers proportioned in accordance with both its height and its width. This sheet of wrapping material is carried upwardly to a suspended position during the downward movement of the carrier from the outfeed station so that the succeeding article can be moved on the carrier when the latter reaches its lower limit of movement at the infeed station. Accordingly, an article is measured and a sheet of wrapping material fed in accordance with the size thereof at each oscillation of the carrier and the carrier thus elevates an article to the outfeed station at each upward movement.

In packaging the products of a commercial bakery a combination of machines embodying the present invention is particularly efficient and economical. The simplicity of operation and adjustment, and the ease with which the wrapping machine can be changed for different article lengths as well as the automatic control of wrapping material length are features attractive to operators and promote economy of time. Safety features to protect the operator, machines, and product have been uniquely combined into a compact structure economical to manufacture and repair.

Furthermore, it is to be understood that the particular form of apparatus shown and described and the particular procedure set forth, are presented for purposes of explanation and illustration and that various modifications of said apparatus and procedure can be made without departing from my invention as defined in the appended claims.

What I claim is:

1. In a wrapping machine having a wrapping mechanism, an infeed station, and an outfeed station, a carrier movable to receive an article at the infeed station and deliver the article at the outfeed station, guide means for the carrier, means for actuating the carrier including an oscillated lever and a link secured to the lever and carrier, a cutter for severing a web of wrapping material and movably mounted adjacent to and in parallel relation with the carrier, and means for actuating the cutter including a reciprocable member actuated by the lever, whereby the carrier and cutter move in synchronization.

2. In a wrapping machine having a wrapping mechanism, an infeed station, an outfeed station, a carrier movable to receive an article at said infeed station and deliver the article at said outfeed station, guide means for the carrier, means for actuating the carrier including an oscillated lever and a link secured to the lever and carrier, a cutter for severing a web of wrapping material, guide means for the cutter arranged in parallel relation with respect to the guide means for the carrier, and means for actuating the cutter including a reciprocable member joined to said link and arranged to move the cutter in synchronization with the carrier.

3. In a wrapping machine having an infeed station, a conveyor to advance articles to said station, a carrier movable to receive the articles at said station and advance them in the machine, said conveyor arranged to individually move each article incompletely onto the carrier, means to feed wrapping material to an article-receiving position adjacent the station while the carrier is removed from the station, whereby, upon movement of an article onto the carrier at the station, the article is partially enveloped by the positioned wrapping material, and means for smoothing the wrapping material against the article as the ar-

5 ticle is advanced by the carrier, said smoothing means arranged to frictionally engage the outer surface of the wrapper and bear against the article with sufficient force to move the article completely onto the carrier.

4. In a wrapping machine having an infeed station, a conveyor to advance articles to said station, a carrier movable to receive the articles at said station and advance them in the machine, said conveyor arranged to individually move each article incompletely onto the carrier, means to feed wrapping material to an article-receiving position adjacent the station while the carrier is removed from the station, whereby, upon movement of an article onto the carrier at the station, the article is partially enveloped by the positioned wrapping material, and means for smoothing the wrapping material against the article as the latter is advanced by the carrier, 10 15 20 25 30 35 40 45 50 55 60 65 70 75

4. In a wrapping machine having an infeed station, a conveyor to advance articles to said station, a carrier movable to receive the articles at said station and advance them in the machine, said conveyor arranged to individually move each article incompletely onto the carrier, means to feed wrapping material to an article-receiving position adjacent the station while the carrier is removed from the station, whereby, upon movement of an article onto the carrier at the station, the article is partially enveloped by the positioned wrapping material, and means for smoothing the wrapping material against the article as the latter is advanced by the carrier, 10 15 20 25 30 35 40 45 50 55 60 65 70 75

5. A wrapping machine, comprising wrapping mechanism and means providing an infeed station adjacent said mechanism, a continuously 30 35 40 45 50 55 60 65 70 75

5. A wrapping machine, comprising wrapping mechanism and means providing an infeed station adjacent said mechanism, a continuously rotating wrapping material feed roller shaft, a wrapping material feed roller and means supporting the same horizontally and generally below the level of said station, means to connect the wrapping material feed roller and the continuously rotating shaft to advance the leading edge of a web of wrapping material in timed relation with the continuously rotating shaft, means for carrying said advanced leading edge upwardly across the infeed station, means for disconnecting the feed roller and continuously rotating shaft to arrest the feeding with the wrapping material web extending upwardly from the feed roller and across the path of an article advancing to the infeed station, and a cutter and means operating the same in timed relation to the disconnecting means for severing the wrapping material adjacent the feed roller after the wrapping material is suspended in a position extending upwardly from the feed roller.

6. In a wrapping machine having a wrapping mechanism and an infeed station, a carrier movable to receive an article at said station and advance it in the wrapping mechanism, means to feed wrapping material beneath the carrier at the infeed station during said advancing movement of the carrier, and means engageable with the under side of the fed wrapping material to carry said engaged portion of the wrapping material upwardly above the level of the carrier at the infeed station and across the path of an article moving toward the carrier.

7. In a wrapping machine having an infeed station and an outfeed station, a carrier for receiving an article at the infeed station and delivering the article at the outfeed station in a partially wrapped condition with a portion of the wrapping material depending from the article, a rotatable roller positioned adjacent the outfeed station and extending substantially across the entire width thereof, the ends of the roller journaled to permit movement of the roller to and from the carrier, said roller and carrier arranged to cooperate to frictionally engage the depending portion of the wrapping material to draw the wrapping material about the article,

resilient means arranged to bear against the center only of the roller to urge the roller toward the carrier, said resilient means including a pressure roll arranged to engage the center only of the roller, and means for adjusting the pressure between the roll and roller, whereby to regulate the degree of frictional engagement of the wrapper.

8. In a wrapping machine having an infeed station and an outfeed station, a carrier for receiving an article at the infeed station and delivering the article at the outfeed station in a partially wrapped condition with a portion of the wrapping material depending from the article, means for moving an article from the carrier over an edge thereof at the outfeed station, a roller on the carrier at said edge, a roller positioned at the outfeed station cooperable with the carrier roller to grip a portion of the wrapping material depending from the article and to draw the wrapping material about the article, one of said rollers being carried in elongated journals to permit substantial lateral movement thereof, and means located between said journals for resiliently pressing the rollers together, whereby said last named roller follows the contour of the other roller to maintain said grip for a substantial period of time while the carrier moves to and away from the outfeed station.

9. In a wrapping machine having an infeed station and an outfeed station, a carrier for receiving an article at the infeed station and delivering the article at the outfeed station in a partially wrapped condition with a portion of the wrapping material depending from the article, means for moving an article from the carrier over an edge thereof at the outfeed station, a roller on the carrier at said edge, a roller positioned at the outfeed station cooperable with the carrier roller to grip a portion of the depending wrapping material and to draw the wrapping material about the article, said outfeed station roller carried in elongated journals to permit substantial movement thereof, whereby the outfeed station roller follows the contour of the carrier roller to maintain said grip for a substantial period of time while the carrier moves to and away from the outfeed station, and means engageable with the center only of the outfeed station roller to urge it against the carrier roller, whereby the rollers are rotated in synchronous relation by the movement of a central part of the depending portion of the wrapping material and the unsupported portions of wrapping material projecting from the ends of an article are supported by the end portions of the rollers and fed thereby in timed relation with the central part of the wrapping material.

10. In a wrapping machine an end folding member supported therein for relative movement with respect to an article being wrapped to perform a folding operation on wrapping material at an end of the article, and an end fold starter carried by the member and having a relative movement toward and away from the folding member during said folding operation, said starter arranged to engage a portion of wrapping material projecting from the end of an article being wrapped and commence to fold said portion against the end of the article prior to the engagement of the wrapper by said member.

11. In a wrapping machine, a top end folding member supported therein for relative movement with respect to an article being wrapped

5 to fold a projecting portion of wrapping material against an end of the article, said relative movement of the member being in a plane closely adjacent the end of the article and the relative movement of the article being substantially parallel to said plane, and a top end fold starter associated with said member and supported thereby, said fold starter being movable toward and away from the folding member to engage said portion of wrapping material projecting from the top of the end of an article being wrapped and commence to fold said portion downwardly against the end of the article prior to the engagement of the wrapper by said member and then move with the wrapper toward the folding member as the fold is completed.

10 12. In a wrapping machine, a top end folding member supported therein for relative movement with respect to an article being wrapped to fold a projecting portion of wrapping material against an end of the article, said relative movement of the member being in a plane closely adjacent the end of the article and the relative movement of the article being substantially parallel to said plane, and a top end fold starter supported adjacent said member and arranged to engage said portion of wrapping material projecting from the top of the end of an article being wrapped and commence to fold said portion downwardly against the end of the article prior to the engagement of the wrapper by said member, said member being yieldably mounted for movement with the article in said plane, and said fold starter being supported farther from the path of the article than the folding member and so that one end thereof moves over the end of the article between the edges of the sides thereof and wrapping material projects beyond said end of the article from one side thereof and beyond the starter while the folding operation is performed.

15 13. In a wrapping machine, a carrier for supporting an article during a wrapping operation with a portion of the wrapping material projecting from underneath an end of the article, means for performing a first end folding operation on a portion of wrapping material projecting from a side of the article at said end, and a top end folder for performing a folding operation on a portion of the wrapping material projecting from the top of the article at said end, said top folder having an element supported thereby in spaced relation to the plane of the folder and directed toward such plane at an oblique angle for engagement with the wrapping material connecting the portion projecting from underneath the article and the portion forming the first end fold to fold said connecting portion of wrapping material against the portion of wrapping material projecting from underneath the article.

20 14. In a wrapping machine having wrapping mechanism, an infeed station and an outfeed station, a carrier movable to receive an article at the infeed station, advance it in the wrapping mechanism and deliver it at the outfeed station, a backing member slidably on the carrier and arranged to engage and guide an article at the infeed station as the article is received on the carrier, said member moving with the article over the carrier, a ram movable to push the article off the carrier at the outfeed station, said ram formed with a recess to receive the backing member, so that the ram engages the article while the latter is engaged by the backing mem-

ber and the ram first disengages the article from the backing member and then moves the backing member to its starting position as the article leaves the carrier and the carrier moves away from the outfeed station, whereby sliding engagement between the backing member and the article is minimized.

15. In a wrapping machine having a carrier for supporting an article during a wrapping operation with an end of wrapping material tucked under the article, a guide member slidably mounted on the carrier and arranged to engage a side of an article moving onto the carrier and move with the article to guide the latter as it is received by the carrier, said guide member having a curved marginal portion along its bottom edge formed to fit the contour of the bottom edge of the article at said engaged side of the article and extend under the said side of the article to minimize relative movement between the tuck-under portion of the wrapping material and the bottom of the article.

16. In a wrapping machine having infeed and outfeed stations, a carrier movable to the infeed station to receive an article and movable to the outfeed station to deliver the article, guide means for the carrier, means for actuating the carrier including an oscillated lever and a link secured to the lever and carrier, a cutter for severing a web of wrapping material, guide means for the cutter, means for actuating the cutter including a reciprocable member joined to said link and actuated thereby to move the cutter in synchronization with the carrier, said cutter guide means being parallel to said carrier guide means whereby the carrier and cutter move in parallel relation to one another, and said member arranged to move the cutter over a path shorter than the path over which the carrier is moved by the link.

17. In a wrapping machine having an infeed station, a conveyor to advance articles to said station, a carrier movable to receive the articles at said station and to advance the received articles in the machine, said conveyor having a member which engages an article to move the same, and which is withdrawn from the article with one side of the article overhanging one edge of the carrier, whereby the conveyor is arranged to individually move each article incompletely onto the carrier, means to feed wrapping material to an article-receiving position adjacent the station and across the path of an article being advanced by said member while the carrier is removed from the station whereby upon movement of an article onto the carrier at the station the article is partially enveloped by the positioned wrapping material, and a plate mounted for pivotal movement adjacent the path of the carrier and an article as the latter is advanced by the carrier, said plate arranged so that one edge thereof first engages a portion of the wrapping material positioned over the top of the article and then a side of the plate progressively smooths the wrapping material over the top and down the side of the article, and said plate being rotated by an advanced article to a position in which the plate presses against said overhanging side of the article to complete the movement of the article onto the carrier as the latter moves away from said station.

18. In a wrapping machine having an infeed station and a carrier to support an article during the wrapping thereof and movable toward and away from the station, means for advancing wrapping material toward the station, means for

5 moving an article onto the carrier at the infeed station, a horizontal member movable upwardly through an arcuate path between the carrier and the article moving means and arranged to engage the under side of wrapping material being advanced and to carry the leading end thereof upwardly and across the path of an article moving onto the carrier at the infeed station, and a clamping member arranged to cooperate with the 10 horizontal member to grip the wrapping material therebetween.

19. In a wrapping machine having infeed and outfeed stations, a carrier for receiving an article at the infeed station and delivering the article 15 at the outfeed station in a partially wrapped condition with a portion of the wrapping material depending from the article, a rotatable roller positioned adjacent the outfeed station and extending substantially across the entire width 20 thereof, said roller being urged against the carrier to frictionally engage therebetween the depending portion of the wrapping material to draw the wrapper about the article, as the latter is moved from the carrier, the ends of said roller being journalled to permit movement of the 25 roller to and from the carrier, resilient means engageable with the center only of the roller to urge the roller toward the carrier, and means to adjust said resilient means whereby the degree of frictional engagement of the wrapper may be selectively regulated.

20. In a wrapping machine having infeed and outfeed stations, a carrier for receiving an article at the infeed station and delivering the article 30 at the outfeed station in a partially wrapped condition with a portion of the wrapping material depending from the article, means for moving an article from the carrier over an edge thereof at the outfeed station, a roller on the 35 carrier at said edge, a roller positioned at the outfeed station, said outfeed station roller being cooperable with the carrier roller to grip a portion of the depending wrapping material and to draw the wrapping material about the article 40 as the article moves off the carrier, said outfeed station roller being carried in elongated journals to permit substantial lateral movement thereof, and resilient means engageable with the outfeed 45 station roller inwardly of the ends thereof for urging the outfeed station roller toward the carrier roller whereby the outfeed station roller follows the contour of the carrier roller to main 50 said grip for a substantial period of time while the carrier moves to and away from the outfeed station.

21. In a wrapping machine, a folding member and means supporting the same for relative movement with respect to an article being wrapped to fold a portion of wrapping material projecting from an end of the article against said end of the article, said relative movement of the member being in a plane closely adjacent the end of the article and the movement of the article through the machine and past said folding member being substantially parallel to said plane, means for carrying the article during said folding operation, and a fold starter associated with said folding member and arranged to engage said projecting portion of wrapping material and commence to fold said projecting portion downwardly against the end of the article prior to the engagement of the wrapping material by said folding member, said starter being movable toward the folding member and supported so as to be moved toward the folding member by the

carrying means as the top end fold is completed.

22. In a wrapping machine having infeed and outfeed stations, a carrier movable to receive an article at the infeed station, advance it in the wrapping mechanism and deliver it at the outfeed station, a pusher to move an article off the carrier at the outfeed station, a reciprocable member to actuate the pusher, and means for slidably securing said pusher to said member whereby upon engagement between the pusher and carrier the pusher may slide on the member to prevent damage to the machine.

23. In a bread wrapping machine, an infeed conveyor, guides above the conveyor for engaging the ends of bread loaves being advanced by the conveyor, a loading tray substantially paralleling the conveyor, said tray having a bottom portion with a supporting surface inclined downwardly and away from the conveyor toward an edge of the tray remote from the conveyor and having an edge adjacent one side of the conveyor and above the level thereof, said surface of the bottom portion being in a plane which passes above the conveyor guides so that a long bread loaf supported on the bottom portion of the tray and projecting over the conveyor is disposed above and clears the top of the guides, a member along the remote lower edge of the tray to retain articles positioned on the inclined surface of the tray, and a supplemental support above said member, said support being substantially parallel to the edge of the tray adjacent the conveyor and substantially level therewith whereby articles may extend across the tray and be supported at their ends by the supplemental support and the tray adjacent the conveyor.

24. In a wrapping machine, wrapping mechanism, means for advancing an article into said mechanism, a roller for intermittently advancing successive lengths of wrapping material to the wrapping mechanism, means for driving the roller during advancing periods at substantially uniform rotational velocity, and measuring means for governing the duration of each roller drive period, said last named means comprising an overhanging member so mounted that it is engaged by an article advancing into the mechanism, and the movement of the member by an article varies with the height and the width of the article, and means for connecting said members with the roller drive means to transmit such movement to said drive means and control the length of wrapping material advanced whereby the length of wrapping material advanced during each drive is determined in accordance with the size of the article advanced.

25. In a wrapping machine, an infeed station, an outfeed station, a carrier movable between the stations and arranged to receive an article at the infeed station and to deliver the article at the outfeed station, said carrier having mounted thereon an end fold starting member and an end fold finishing member, said starting member being movable on the carrier and normally supported to project in advance of the finishing member and arranged to commence an end fold in a wrapper on a received article prior to the engagement of such wrapper by the finishing member, and means for moving the fold starting member away from the article to permit a further wrapping operation to be performed on the end of the article.

26. In a wrapping machine having wrapping mechanism, an infeed station and an outfeed station, a carrier movable to receive an article at

the infeed station, advance it in the wrapping mechanism and deliver it at the outfeed station, a reciprocable member actuated for movement across the path of the carrier at the outfeed station, and a pusher carried by the member to engage and move an article off the carrier, said pusher having a sliding connection with the reciprocable member in the direction of carrier movement to permit relative movement between the pusher and the reciprocable member upon engagement between the pusher and the carrier to prevent damage to the machine.

27. In a wrapping machine, a channel shaped sealed, movable carrier means for supporting and delivering a succession of articles to the sealer at timed intervals, means for moving the articles from the carrier to the sealer, a discharge conveyor supported and extending as a continuation of the sealer and so that at each delivery of an article to the sealer the articles in the sealer are advanced and an article is moved from the sealer to the conveyor, a pusher member and means for actuating the same for movement above the carrier and through the sealer in timed relation to said intervals to clear articles from the sealer, and means supporting said pusher so as to be engaged by an article on the carrier and held thereby out of engagement with articles previously advanced into the sealer, whereby the clearing of the sealer occurs only after movement of the carrier to the sealer without an article.

28. In a wrapping machine having an outfeed station and a folding channel, a carrier for supporting an article being wrapped and movable to convey said article to said station, a reciprocable member and means for actuating the same to engage a side of the conveyed article to move the article from the carrier to the folding channel and to then be withdrawn from the article and returned to move the next article, and means supported to engage said side of the article when the article is in the folding channel prior to the withdrawal of the reciprocable member from the article to prevent reversal of the direction of movement of the article in the channel.

29. In a wrapping machine having a wrapping mechanism, an infeed station and an outfeed station, a carrier movable to receive an article at the infeed station, advance the article in the wrapping mechanism, and deliver the article at the outfeed station, and means to move said carrier, said means including a reciprocable member and drive means to oscillate the same over an arcuate path exceeding 180°, and means connecting the member and carrier for synchronous movement so that the member is at one end of said path when the carrier is at the infeed station and at the other end of said path when the carrier is at the outfeed station.

30. In a wrapping machine, a carrier, an infeed station, an outfeed station, and means including a drive member traveling in an arcuate path and a connecting member attached to the drive member to move the carrier to receive an article at said infeed station, to advance the article in the wrapping mechanism and to deliver the article at said outfeed station, said connecting member and drive member being actuated to move past dead center and then reverse their direction of movement while the carrier is at one of the stations to effect a slight oscillation of the carrier toward and away from the other station.

31. In a wrapping machine, a carrier, an infeed station, an outfeed station, means to move the carrier to receive an article at said infeed station

and to deliver the article at said outfeed station, and guide means for the carrier, said carrier moving means including an oscillating lever and means connecting the carrier to the lever for synchronous movement therewith and so that the carrier is at the infeed station when the lever is at one limit of movement and at the outfeed station when the lever is at the other limit of movement, and means for oscillating said lever through more than 180° whereby the connecting means is carried across dead center while the carrier is adjacent one of the stations and the prolonged movement of the connecting means back and forth across dead center effects a dwell of the carrier at such station.

32. In a wrapping machine having a reciprocable carrier, means for reciprocating the carrier comprising a rotatable drive shaft and drive means therefor, a crank secured to the shaft for rotation therewith, a toothed reciprocable member, means connecting the crank and the member to reciprocate the latter upon rotation of the drive shaft, a driven shaft having a gear meshing with the teeth of the reciprocable member so that the driven shaft is oscillated by the reciprocation of the member, an arm secured on the driven shaft, and means connecting the arm and the carrier to actuate the carrier in timed relation to the oscillation of the driven shaft.

33. In a wrapping machine having a reciprocable carrier, means for reciprocating the carrier comprising a rotatable drive shaft and drive means therefor, a crank secured to the shaft for rotation therewith, a toothed reciprocable member, means connecting the crank and the member to reciprocate the latter upon rotation of the driveshaft, a driven shaft having a gear meshing with the teeth of the reciprocable member so that the driven shaft is oscillated by the reciprocation of the member, the radius of the gear on the shaft being proportioned with respect to the movement of the reciprocable member to oscillate the driven shaft through more than 180°, an arm secured on the driven shaft, and means connecting the arm and the carrier to actuate the carrier in timed relation to the oscillation of the driven shaft.

34. In a wrapping machine having a reciprocable carrier, means for reciprocating the carrier comprising a rotatable drive shaft and drive means therefor, a driven shaft connected to the carrier, and means connecting the shafts to oscillate the driven shaft through more than 180° for every revolution of the drive shaft.

35. In a wrapping machine having a reciprocable carrier, means for reciprocating the carrier comprising a rotatable drive shaft and drive means therefor, a driven shaft connected to the carrier, a sector connected to the drive shaft to be reciprocated thereby, and means on the driven shaft connected to the sector and proportioned relative thereto to oscillate the driven shaft through more than 180° during each reciprocation of the sector.

36. In a wrapping machine, means for supporting a partially wrapped article with wrapping material positioned over the top and down a side thereof, a smoothing member including a substantially flat surfaced wrapping material engaging element, means pivotally supporting the element, and means for causing relative movement of a supported article and the element so that the latter passes over the top and down a side of the article with said surface in con-

tinuous frictional engagement with the wrapping material.

37. In a wrapping machine, means for supporting a partially wrapped article with the wrapping material positioned over the top and down a side thereof, a smoothing member including a substantially flat surfaced wrapping material engaging element, means pivotally supporting the element, means for causing relative movement of a supported article and the element so that the latter passes over the top and down a side of the article with said surface in continuous frictional engagement with the wrapping material, and means for retaining said flat surface of the element substantially parallel to the line of relative movement of the article and member as the element moves over the side of the article.

38. In a wrapping machine, a wrapping mechanism, an article advancing mechanism, a driven shaft rotating at substantially constant speed in timed relation to the operation of the wrapping mechanism, wrapping material feeding mechanism having means connectable to said shaft for feeding wrapping material into the wrapping mechanism, means for engaging said wrapping material and moving the same to a position adjacent the wrapping mechanism and in the path of an article advancing into the mechanism, an overhanging member so mounted in the machine that the movement of the member by an advancing article varies with the height and width of such article, and means connecting the overhanging member to the wrapping material advancing means to transmit such movement to the wrapping material advancing means and control the connection of the latter to said shaft to thereby control the length of wrapping material fed, and means operating in timed relation to the wrapping mechanism to sever the fed wrapping material.

39. In a wrapping machine, a wrapping mechanism, means for feeding a wrapping material web and severing individual sheets therefrom, a movable size indicator, means for moving an article to be wrapped past the indicator to move the same and be gauged thereby, said indicator being so mounted that the movement of the same by the article varies with the height and width of the article, and means connecting the indicator to the feeding mechanism to transmit such movement to the feeding mechanism and control the length of wrapper fed for proportioning the length of sheet severed in accordance with the size of the article gauged.

40. In a wrapping machine, wrapping mechanism and means for driving the same for cyclic operation, means for feeding one end of a web of wrapping material to a position adjacent the wrapping mechanism, means for actuating the feeding means synchronously with the wrapping mechanism and including means for stopping the feeding at a predetermined position of the wrapping mechanism in a wrapping cycle, a cutter for severing the fed end of the wrapper after the wrapping mechanism has passed said position, means for advancing an article to the wrapping mechanism in timed relation to the cycle thereof, a movable article size indicator so mounted that the movement of the same by the article varies with the height and width of the article, and means connecting the indicator to the wrapping material feeding means to transmit such movement to said feeding means and control the starting of the feeding means at such time relative to the wrapping cycle that the size of the

wrapping material fed is proportioned in accordance with the height and width of the article being advanced prior to the stopping of the feeding means.

41. In a wrapping machine, wrapping mechanism, wrapping material feeding mechanism, means for advancing articles into the wrapping mechanism, a member so mounted that it is engaged and moved by an advancing article, means connecting the member to the feeding mechanism to actuate such mechanism in response to the movement of an article into the wrapping mechanism to feed a length of wrapping material to the wrapping mechanism, and a movable member in said connection adjustable to different positions to vary the connection and alter the time of the actuation with respect to the position of the article being advanced, said movable member having means associated therewith to retain the same in adjusted position.

42. In a wrapping machine, wrapping mechanism, a driven shaft rotating at substantially constant speed, wrapping material feeding mechanism and means for connecting the same to said shaft for a period of time to advance a length of wrapping material into the wrapping mechanism, means for advancing an article into the wrapping mechanism, a member so mounted that it is engaged and moved by an advancing article, means connecting the member to the wrapping material feeding mechanism to govern the connection of the latter to the driven shaft in response to the movement of the member by an article, and a movable member in said last named connection adjustable to different positions to vary the time of connecting the feeding mechanism to the driven shaft with respect to the position of the article being advanced, said movable member having means associated therewith to retain the same in adjusted position.

43. In a wrapping machine, wrapping mechanism, means for rotatably supporting a supply roll of wrapping material, a pair of feed rolls and drive means for the same to advance wrapping material from the supply roll to the mechanism as required, a booster roll driven for continuous rotation and positioned to frictionally engage wrapping material extending between the supported supply roll and the feed rolls, means for taking up slack in the wrapping material between the booster roll and the feed rolls, and means for actuating the feed rolls in timed relation to the wrapping mechanism, said feed roll actuating means including an overhanging member so mounted that the movement of the same by an article being advanced into the wrapping mechanism varies with the height and width of such article, and means connecting said overhanging member to the feed roll drive to control the length of wrapping material advanced in proportion to the size of the article being advanced into the mechanism.

44. In a wrapping machine having an infeed station and an outfeed station, a carrier movable to receive an article at said infeed station and to deliver the article at said outfeed station, a movable cutter, means to feed a wrapping material web across said cutter, means for carrying a free end of the fed web to an article receiving position across the infeed station while the carrier is removed from the infeed station and so that the last fed portion of wrapping material is positioned approximately parallel to the cutter path, actuating means to move the cutter synchronously with the carrier to sever the web while

the carrier is adjacent the infeed station, and a member movable with the cutter and arranged to move said last fed wrapping portion to a position at a material angle to the cutter path prior to the severing of the web.

45. In a wrapping machine, feeding mechanism for advancing wrapping material, a pair of elongated gripper members, means supporting said members horizontally for movement over an arcuate path, and means for actuating the members to engage opposite sides of fed wrapping material to grip the same therebetween when the members are in the lower portions of their path and to carry said engaged wrapper upwardly over said path.

46. In a wrapping machine, feeding mechanism for advancing wrapping material, a horizontal wrapper positioning member, means for supporting said member for movement over an arcuate path, and means for actuating the member to engage the underside of fed wrapping material and to carry said engaged wrapping material upwardly over said path.

47. In a wrapping machine, feeding mechanism for advancing wrapping material, a pair of elongated gripper members, means supporting said members horizontally for movement over an arcuate path, means for actuating the members to engage opposite sides of fed wrapping material to grip the same therebetween when the members are in the lower portions of their path and to carry said engaged wrapper upwardly over said path, and a supplementary member disposed adjacent the upper end of the path of said gripper members to momentarily bear against one of the gripper members with the fed wrapping material engaged therebetween and with sufficient friction to yieldingly hold the wrapper.

48. In a wrapping machine having an infeed station and an outfeed station, a carrier for receiving an article at the infeed station and delivering the article at the outfeed station in a partially wrapped condition with a portion of the wrapping material depending from the article, a friction element positioned adjacent the outfeed station and arranged to bear against the carrier to frictionally engage the depending portion of the wrapping material to draw the latter about the article, resilient means mounted to press against the center only of the element to force the same against the wrapping material and the carrier, and a manually operable member movable to vary the pressure of the resilient means against the element while the machine continues in operation to selectively regulate the degree of said frictional engagement.

49. In a bread wrapping machine having an infeed conveyor for advancing loaves to be wrapped, guides above the conveyor for engaging the ends of loaves being advanced, a loading tray supported adjacent the conveyor and comprising a substantially flat bottom portion the upper surface of which is inclined downwardly and away from one side of the conveyor at a relatively small angle with the horizontal, said surface of the bottom portion being in a plane which passes above the conveyor guides so that a long bread loaf supported on the bottom portion of the tray and projecting over the conveyor clears the tops of the guides, an upright retaining member along the lower edge of the bottom portion and disposed at substantially a right angle thereto, and a horizontal support portion extending along the top edge of the re-

taining member, said support portion being in spaced parallel relation to said side guides and approximately level with the conveyor.

50. The method of wrapping an article in a machine having a reciprocable carrier which comprises supporting and advancing the article over an approximately horizontal path to said carrier, feeding the free end of a continuous web of wrapping material upwardly across that portion of the path of the advancing article which the article traverses before reaching the carrier to locate a portion of the wrapping material in position to intercept the advancing article, severing said located portion of wrapping material from the continuous web thereof before the wrapping material is engaged by the advancing article, supporting the severed wrapping material in suspended position across the article path and for yielding movement so that the movement of the article drapes the wrapping material over the top and down the sides of the article with portions of the wrapping material projecting beyond the ends of the article, tucking the ends of the draped wrapping material under the article, folding the projecting portions of wrapping material against the article, and sealing overlapped portions of the wrapping material to secure the folds in place.

51. In a wrapping machine an end folding member supported therein for relative movement with respect to an article being wrapped to perform a folding operation on wrapping material at one end of the article, a rod supported and guided by said member for longitudinal sliding movement, and an end fold starter mounted on the rod for relative movement toward and away from the folding member during said folding operation, said starter being arranged to engage a portion of wrapping material projecting from the end of an article being wrapped and to commence folding said engaged portion against such end of the article prior to the engagement of the wrapper by said end folding member.

52. In a wrapping machine having an end folding member and a carrier reciprocable to and from the member for raising an article being wrapped to move the latter across said member to perform a folding operation on wrapping material at one end of the article, an end fold starter carried by the end folding member and movable toward and away from the latter, said starter being arranged to engage a portion of wrapping material projecting from the end of an article as the latter is raised by the carrier and commence folding said portion against the end of the article prior to the engagement of the wrapping material by the folding member, and the starter being moved toward the folding member by the carrier during the completion of the folding operation.

53. In a wrapping machine having an end folding member and a carrier reciprocable to and from the member for raising an article being wrapped to move the latter across said member to perform a folding operation on wrapping material at one end of the article, an end fold starter suspended from the end folding member and movable toward and away from the latter, said starter being normally positioned to engage a portion of wrapping material projecting from one end of an article at the top thereof as the article is raised by the carrier and commence folding said engaged portion downwardly against the end of the article prior to the engagement

of the wrapping material by the folding member, the starter being engaged and moved toward the folding member by the carrier during the completion of the folding operation, and the starter being arranged to engage another portion of wrapping material projecting from said end of the article to hold such other portion against the carrier while the starter is moved by the carrier.

54. In a wrapping machine having an end folding member and a carrier reciprocable to and from the member for raising an article being wrapped to move the latter across said member to perform a folding operation on wrapping material at one end of the article, an end fold starter suspended from the end folding member and movable toward and away from the latter, said starter being normally positioned to engage a portion of wrapping material projecting from one end of an article at the top thereof as the article is raised by the carrier and commence folding said engaged portion downwardly against the end of the article prior to the engagement of the wrapping material by the folding member, the starter being moved toward the folding member by the carrier during the completion of the folding operation, the starter being arranged to engage another portion of wrapping material projecting from said end of the article to hold such other portion against the carrier while the starter is moved by the carrier, and means separating the starter and the carrier to provide a narrow space for movement of said other portion of wrapping material as the article is moved laterally off the carrier upon completion of said folding operation.

55. In a wrapping machine having a supporting structure and a movable carrier supported therein, a member mounted on the carrier to engage and fold wrapping material against one end of an article as the latter is received on the carrier, a fold starter movably mounted on the carrier and projecting beyond the folding member to engage the wrapping material on an article and commence folding the wrapping material prior to the engagement of such wrapping material by the folding member, and means having connection with the fold starter and coacting with the supporting structure during movement of the carrier to move the fold starter away from the end of an article on the carrier to permit a further wrapping operation to be performed on the article.

56. In a wrapping machine having a supporting structure and a movable carrier supported therein, a member mounted on the carrier to engage and fold wrapping material against one end of an article as the latter is received on the carrier, a fold starter disposed alongside the folding member to engage the wrapping material on an article and commence to fold the same prior to the engagement of such wrapping material by the folding member, means pivotally mounting the fold starting member on the carrier for swinging movement toward and away from the folding member, and means having connection with the fold starter and coacting with the supporting structure during movement of the carrier to swing the fold starter away from said end of the article on the carrier to permit a further wrapping operation to be performed on the article.

57. In a wrapping machine having a supporting structure and infeed and outfeed stations, a reciprocable carrier supported in the structure,

said carrier being movable to the infeed station to receive an article to be wrapped and movable to the outfeed station to discharge such article, a member mounted on the carrier for movement therewith and for lateral bodily movement relative thereto, said member being normally disposed to engage and fold wrapping material against an end of an article as the latter is received by the carrier at the infeed station, and means having connection with the folding member and coacting with the structure during movement of the carrier to the outfeed station to move the member bodily away from normal position and the end of the received article to permit a further wrapping operation on said end of the article while the latter is on the carrier.

58. In a wrapping machine having a supporting structure and infeed and outfeed stations, a reciprocable carrier supported in the structure, said carrier being movable to the infeed station to receive an article to be wrapped and movable to the outfeed station to discharge such article, a member to engage and fold wrapping material against an end of an article as the latter is received by the carrier at the infeed station, means pivotally mounting the member on the carrier for movement therewith and for lateral bodily swinging movement relative thereto, and means having connection with the folding member and coacting with the structure during the movement of the carrier to the outfeed station to swing the folding member bodily outwardly and upwardly from the end of a received article subsequent to said engagement of the wrapping material thereby, to permit a further wrapping operation on said end of the article while the latter is on the carrier.

59. In a wrapping machine having mechanism for feeding wrapping material, a pair of wrapper positioning members, means for supporting said members in horizontal positions substantially parallel to one another and for simultaneous movement over an arcuate path, and means for actuating the members to engage the underside of fed wrapping material and to carry said engaged wrapping material upwardly over said path.

60. In a wrapping machine having mechanism for feeding wrapping material, a pair of wrapper positioning members, means for supporting said members in horizontal positions substantially parallel to one another and for simultaneous movement over an arcuate path, an elongated clamping member, and means for actuating the members to grip fed wrapping material between the clamping member and one of the positioning members when the latter are in the lower portions of their path and to carry the gripped wrapper upwardly over said path.

61. In a wrapping machine having a supporting structure and mechanism for feeding wrapping material, an elongated wrapper positioning member, an arm pivoted on the structure and connected to the member to support the same in horizontal position for movement over an arcuate path between parallel positions spaced above and below the plane of fed wrapping material, and means for actuating the member in synchronism with said mechanism to engage the underside of fed wrapping material and to carry said engaged wrapping material upwardly over said path.

62. In a wrapping machine having a supporting structure and mechanism for feeding wrapping material, a pair of elongated gripper members, arms pivoted on the structure and con-

nected to the members to support the same horizontally for movement over an arcuate path, and means for actuating the members to engage opposite sides of fed wrapping material to grip the same therebetween when the members are in the lower portion of their path and to carry the engaged wrapper upwardly over said path.

63. In a wrapping machine having a supporting structure and mechanism for feeding wrapping material, an elongated wrapper positioning member, an arm pivoted on the structure and connected to the member to support the same in horizontal position for movement over an arcuate path, an elongated clamping member, a second arm pivoted on the first mentioned arm and connected to the clamping member to support the same horizontally for movement over a curved path, and means for actuating the members to separate and receive fed wrapping material therebetween in the lower portions of said paths and to then move together to grip the received wrapping material and to carry the gripped wrapping material upwardly over said paths.

64. In a wrapping machine having a supporting structure and mechanism for feeding wrapping material over a generally horizontal path, a pair of elongated gripper members, means supporting said members horizontally for movement over an arcuate path crossing said wrapping material path, means restricting the movement of one of the members to the portion of the arcuate path above the horizontal path, and means for actuating the members so that the other member first moves downwardly to a position below the horizontal path to underlie fed wrapping material and then moves upwardly to carry the fed wrapping material over said arcuate path, the members cooperatively engaging the wrapping material to grip the same during the movement over the portion of the arcuate path above the wrapping material path.

65. In a wrapping machine having a supporting structure and mechanism for feeding wrapping material over a generally horizontal path, a pair of elongated gripper members, means supporting said members horizontally for movement over an arcuate path crossing said wrapping material path, means restricting the movement of one of the members to the portion of the arcuate path above the horizontal path, means for actuating the members so that the other member first moves downwardly to a position below the horizontal path to underlie fed wrapping material and then moves upwardly to carry the fed wrapping material over said arcuate path, the members cooperatively engaging the wrapping material to grip the same during the movement over the portion of the arcuate path above the wrapping material path, and means for moving the members away from one another at the upper end of the arcuate path to release the carried wrapping material.

66. In a wrapping machine having a supporting structure and mechanism for feeding wrapping material over a generally horizontal path, an elongated wrapper positioning member and means for horizontally supporting the same for movement over an arcuate path crossing the wrapping material path, means for actuating said member to first move downwardly to a position below the horizontal wrapping material path and to then move upwardly under fed wrapping material to carry the latter over the arcuate path, an elongated gripper member and means for horizontally supporting the same to rest by grav-

ity on the wrapper positioning member and to move therewith over the arcuate path, and means effecting a relative separating movement between the members at the ends of the arcuate path to permit fed wrapping material to be received therebetween in the region of the wrapping material path and to release the carried wrapping material at the upper end of the arcuate path.

67. In a wrapping machine having a supporting structure and mechanism for feeding wrapping material over a generally horizontal path, an elongated wrapper positioning member and means for horizontally supporting the same for movement over an arcuate path crossing the wrapping material path, means for actuating said member to first move downwardly to a position below the horizontal wrapping material path and to then move upwardly under fed wrapping material to carry the latter over the arcuate path, an elongated gripper member and means for horizontally supporting the same to rest by gravity on the wrapper positioning member and to move therewith over the arcuate path, and means restricting the movement of the gripper member to the portion of the arcuate path above the wrapping material path so that the positioning member moves away from the gripper member at the lower end of the arcuate path to receive fed wrapping material therebetween whereby the wrapping material is clamped between the positioning member and the gripping member during the movement over the upper portion of the arcuate path.

68. In a wrapping machine having a supporting structure and mechanism for feeding wrapping material over a generally horizontal path, an elongated wrapper positioning member and means for horizontally supporting the same for movement over an arcuate path crossing the wrapping material path, means for actuating said member to first move downwardly to a position below the horizontal wrapping material path and to then move upwardly under fed wrapping material to carry the latter over the arcuate path, an elongated gripper member and means for horizontally supporting the same to rest by gravity on the wrapper positioning member and to move therewith over the arcuate path, means restricting the movement of the gripper member to the portion of the arcuate path above the wrapping material path so that the positioning member moves away from the gripper member at the lower end of the arcuate path to receive fed wrapping material therebetween whereby the wrapping material is clamped between the positioning member and the gripping member during the movement over the upper portion of the arcuate path, and means for raising the gripper member off the positioning member at the upper end of the arcuate path to release the clamped wrapping material.

69. In a wrapping machine having a wrapping mechanism and an infeed station, means for advancing an article over an infeed path and into the mechanism at said station, means for feeding wrapping material to a position generally below said station and path, a wrapper positioning member and means supporting the same horizontally for movement over an arcuate path crossing the infeed path, and means for actuating said member to engage the underside of fed wrapping material and to carry the engaged wrapping material upwardly over the arcuate path ahead of an advancing article whereby the wrapping material is disposed to

be engaged by such article and drawn thereby into the wrapping mechanism.

70. In a wrapping machine having a wrapping mechanism and an infeed station, means for advancing an article over an infeed path and into the mechanism at said station, means for feeding wrapping material to a position generally below said station and path, a pair of elongated gripper members and means supporting the same horizontally for movement over a path crossing the article path, and actuating means including means for separating the members at the lower end of their path to receive fed wrapping material therebetween, and means for bringing the members together to clamp the received wrapping material and then moving the grippers in unison to carry the wrapping material upwardly over the gripper path ahead of an advancing article whereby the wrapping material is disposed to be engaged by such article and drawn thereby into the wrapping mechanism.

71. Apparatus in combination including wrapping mechanism, means for advancing an article into the mechanism over an infeed path, means for feeding wrapping material to a position in the apparatus generally below said path, means engageable with fed wrapping material and movable to carry the wrapping material upwardly to a suspended position across said path, and actuating means synchronized with the article advancing means to first move the carrying means to position wrapping material in front of an advancing article so that the article engages the wrapping material to carry the same into the mechanism and to then move the carrying means downwardly behind an advanced article to draw the wrapping material around and down the rear side of the article.

72. Apparatus in combination including wrapping mechanism, means for advancing an article into the mechanism over an infeed path, means for feeding wrapping material to a position in the apparatus generally below said path, gripper means separable to receive wrapping material therebetween and movable to carry fed wrapping material upwardly across the article path, and actuating means synchronized with the advancing means to first move the gripper means in unison to carry wrapping material upwardly in front of an advancing article so that the article engages the wrapping material to carry the same into the mechanism and to then move the gripper means downwardly behind an advanced article to draw the wrapping material around and down the rear side of the article under tension, said actuating means including means for separating the gripper means momentarily during the engagement of the article and the wrapping material to release the latter for movement with the advancing article whereby fed wrapping material is clamped between the grippers while being carried across the article path, released by the grippers during the movement of the article into the mechanism, and again clamped between the grippers as they draw the same down the rear of the article to tension the wrapping material.

73. In a wrapping machine having an infeed station and a reciprocable article carrier movable to and from the station, means for advancing an article to the carrier at said station over an infeed path, means for feeding wrapping material to a position generally below the station, means engageable with fed wrapping material and movable to carry the same upwardly across

the article path, actuating means for the carrying means including an oscillatable shaft, and drive means comprising a driven shaft and means for oscillating the same, a connection including a link between the driven shaft and the article carrier, and a connection including a link between the driven shaft and said oscillatable shaft, said connections being arranged so that the carrying means is moved downwardly across the article path to below the position of fed wrapping material while the article carrier is moved away from the infeed station and the carrying means is moved upwardly to engage fed wrapping material and carry the same across the article path while the article carrier is returned to the infeed station.

74. In a wrapping machine having side and bottom members providing a folding channel open at its ends, a carrier and means for actuating the same to raise a partially wrapped article to the level of the channel, said side members including folders which project beyond the bottom member and normally engage projecting portions of wrapping material on an article being raised to fold the same downwardly against the ends of the article and heated plates which seal the folded wrapping material, and means pivotally supporting the side members at the ends thereof remote from the folders so that the folder and sealing plate of each side member of the channel move on the pivot means as a unit upon engagement between the folder and an article raised by the carrier and misplaced thereon.

75. In a wrapping machine having a reciprocable carrier for advancing articles, a reciprocable cutter, means for actuating the carrier and cutter in synchronism and so that the carrier moves toward and away from the cutter during each reciprocation thereof, means for feeding a wrapping material web across the path of the cutter, means for carrying the fed web to an article receiving position in which the last fed portion thereof is approximately parallel to the cutter path, a member carried by the cutter and movable to shift said last fed portion of wrapping material to a position at a material angle to the cutter path, and means having connection with said member and coacting with the carrier to move the member to shift the wrapping material as the carrier moves toward the cutter and prior to the severing of the wrapping material by the cutter.

76. In a wrapping machine having a carrier and a cutter, means for actuating the carrier and the cutter to reciprocate in synchronism and to move the carrier toward and away from the cutter during each reciprocation, means for feeding wrapping material across the path of the cutter, a member carried by the cutter and movable relative thereto for engaging fed wrapping material, and means connected to said member and coacting with the carrier to move the member away from the cutter as the carrier moves toward the cutter and to engage the fed wrapping material to shift the latter away from the cutter.

77. In a wrapping machine having a carrier and a cutter and means guiding the same for reciprocation over parallel paths, means for feeding wrapping material in a direction transverse to said paths, means for synchronously actuating the cutter and the carrier for simultaneous reciprocation and so that they move relatively toward one another, a member pivotally mount-

ed on the cutter for reciprocation therewith, and means having connection with said member and coacting with the carrier to move the member away from the cutter as the carrier and the cutter move toward one another, whereby the member engages fed wrapping material disposed alongside the cutter to shift the same away from the cutter.

78. In a wrapping machine having a heated sealer, a carrier for advancing articles to the sealer, a reciprocable ram for moving articles from the carrier and past the sealer, the sealer extending beyond the limit of ram movement so that each article is released by the ram while in contact with the sealer and normally so remains until pushed beyond the sealer by the next article, a pusher carried by the ram for reciprocation therewith, and means supporting the pusher to extend ahead of the ram in position to engage a previously released article to push the latter beyond the sealer, said pusher being disposed in the path of articles advanced by the carrier so as to be displaced from said position, whereby advanced articles normally displace the pusher to avoid engagement between the latter and a previously released article and the pusher is operative to push a released article beyond the sealer in the absence of a displacing article on the carrier.

79. In a wrapping machine having a heated sealer providing a generally horizontal path for wrapped articles, a reciprocable carrier for intermittently elevating articles to said path, a reciprocable ram movable to engage an elevated article and advance the same along said path, a pusher carried by the ram for reciprocation therewith and disposed to extend ahead of the ram and normally rest by gravity in raised position on the tops of articles elevated by the carrier as such articles are advanced along the sealer path by the ram, and means supporting the pusher in lowered position in the absence of an article on the carrier so that the pusher engages articles previously advanced into the sealer path and advances such articles during the ram movement.

80. In a wrapping machine having a heated sealer providing a generally horizontal path for wrapped articles, a reciprocable carrier for intermittently elevating articles to said path, a reciprocable ram movable to engage an elevated article and advance the same along said path, a pusher carried by the ram for reciprocation therewith and disposed to extend ahead of the ram and normally rest by gravity in raised position on the top of articles elevated by the carrier as such articles are advanced along the sealer path by the ram, means for actuating the ram including a reciprocating arm, and link means extending between the arm and the pusher to support the latter in lowered position in the absence of an article on the carrier so that the pusher engages articles previously advanced into the sealer path and advances such articles during the ram movement.

81. In a wrapping machine having a heated sealer providing a generally horizontal path for wrapped articles, a reciprocable carrier for intermittently elevating articles to said path, a reciprocable ram movable to engage an elevated article and advance the same along said path, a pusher carried by the ram for reciprocation therewith and disposed to extend ahead of the ram and normally rest by gravity in raised position on the tops of articles elevated by the car-

rier as such articles are advanced along the sealer path by the ram, means for actuating the ram including a reciprocating arm, and link means extending between the arm and the pusher to support the latter in lowered position in the absence of an article on the carrier so that the pusher engages articles previously advanced into the sealer path and advances such articles during the ram movement, said arm and link means being operative to lift the pusher to raised position during the elevation of articles to said path and to release the pusher to said gravity position during the advancing movement of the ram.

82. In a wrapping machine, feeding mechanism for advancing wrapping material, a horizontal wrapper positioning member, means for supporting said member for movement over an arcuate path, means for actuating the member to engage the underside of fed wrapping material and to carry the same upwardly over said path, and means supported adjacent said path for movement in parallelism with and cooperative with the member while the latter moves over said arcuate path to grip the wrapping material.

83. In a wrapping machine, feeding mechanism for advancing wrapping material, a horizontal wrapper positioning member, means for supporting said member for movement over an arcuate path, means for actuating the member to engage the underside of fed wrapping material and to carry the same upwardly over said path, holding means mounted for movement in parallelism with and cooperative with the member to momentarily grip the wrapping material therebetween while the member moves over said arcuate path, and means for supporting the holding means in a relatively stationary position adjacent said path to limit the period of cooperative gripping of the wrapping material.

84. In a wrapping machine having means for advancing articles to be wrapped along an infeed path and means for feeding wrapping material, gripper means for firmly engaging fed wrapping material and actuating means for moving the gripper means to spread the wrapping material across the path in a suspended position and then release the wrapping material, and means for holding the spread wrapping material upon release thereof in said position less firmly than the gripper means while an advancing article engages the wrapping material and draws the same about the article.

85. In a wrapping machine having an infeed station and a carrier to support an article during the wrapping thereof and movable toward and away from said station, means for feeding wrapper material along a path generally below said station, means for advancing an article over an infeed path generally above the wrapper path and onto the carrier at said station, a carrier member movable across said paths and means for actuating the same to move upwardly and engage the underside of a fed wrapper to carry the latter across the article path and spread the same ahead of an article advancing onto the carrier, and a clamping member cooperative with the carrier member to grip the spread wrapper.

86. In a wrapping machine having an infeed station and a carrier to support an article during the wrapping thereof and movable toward and away from said station, means for feeding wrapper material along a path generally below said station, means for advancing an article over an

infeed path generally above the wrapper path and onto the carrier at said station, a carrier member movable across said paths and means for actuating the same to move upwardly and engage the underside of a fed wrapper to carry the latter across the article path and spread the same ahead of an article advancing onto the carrier, and a holding member and means yieldingly supporting the same in a relatively stationary position in the path of the movable carrier member to be displaced by the latter during its upward movement whereby the holding and movable carrier members cooperate to yieldingly grip a spread wrapper and an advancing article engaging the gripped wrapper draws the latter between the members.

87. In a wrapping machine having an infeed station and a carrier to support an article during the wrapping thereof and movable toward and away from said station, means for feeding wrapper material along a path generally below said station, means for advancing an article over an infeed path generally above the wrapper path and onto the carrier at said station, a carrier member movable across said paths and means for actuating the same to move upwardly and engage the underside of a fed wrapper to carry the latter across the article path and spread the same ahead of an article advancing onto the carrier, a clamping member movable with the carrier member and cooperative therewith to grip the fed wrapper during the spreading thereof, means operative to move the clamping member to release the spread wrapper, and a holding member disposed to yieldingly bear against the carrier member when the wrapper is released to yieldingly grip the latter therebetween.

88. In a wrapping machine having an infeed station and a carrier to support an article during the wrapping thereof and movable toward and away from said station, means for feeding wrapper material along a path generally below said station, means for advancing an article over an infeed path generally above the wrapper path and onto the carrier at said station, means reciprocable across said paths and actuatable to grip a fed wrapper to first carry the wrapper upwardly across the article path to spread the same ahead of an article advancing to the carrier and to then draw the wrapper downwardly behind an advanced article to enwrap the article and tension the wrapper thereabout, and means for actuating the reciprocable means in synchronism with the article advancing means.

89. In a wrapping machine having an infeed station and a carrier to support an article during the wrapping thereof and movable toward and away from said station, means for feeding wrapper material along a path generally below said station, means for advancing an article over an infeed path generally above the wrapper path and onto the carrier at said station, means reciprocable across said paths and actuatable to grip a fed wrapper to first carry the wrapper upwardly across the article path to spread the same ahead of an article advancing to the carrier and to then draw the wrapper downwardly behind an advanced article to enwrap the article and tension the wrapper thereabout, means for actuating the reciprocable means in synchronism with the article advancing means, and means operative to momentarily release the grip of the reciprocable means on the spread wrapper to permit the advancing article to carry the wrapper along the article path.

90. In a wrapping machine having an infeed station and a carrier to support an article during the wrapping thereof and movable toward and away from said station, means for feeding wrapper material along a path generally below said station, means for advancing an article over an infeed path generally above the wrapper path and onto the carrier at said station, means reciprocable across said paths and actuatable to grip a fed wrapper to first carry the wrapper upwardly across the article path to spread the same ahead of an article advancing to the carrier and to then draw the wrapper downwardly behind an advanced article to enwrap the article and tension the wrapper thereabout, means for actuating the reciprocable means in synchronism with the article advancing means, means operative to momentarily release the grip of the reciprocable means on the spread wrapper to permit the advancing article to carry the wrapper along the article path, and holding means for yieldingly engaging the upper part of the spread wrapper during said release to yieldingly support the same while the lower part of the wrapper is carried along by the advancing article.

91. In a wrapping machine having a supporting structure, a discharge conveyor having spaced guides, support members mounted on the structure for movement toward and away from one another and connected to the guides to support

the latter, spaced side members and a bottom member defining a sealing channel, the bottom member being in line with the conveyor and the side members being in line with the guides and normally extending over the bottom member, and means mounting the side members on the support members for pivotal movement about horizontal axes so that the side members move in unison with the guides and so that the side members can be pivoted upwardly away from the bottom member while maintaining a constant spacing between the side members.

92. In a wrapping machine having wrapping mechanism and means for advancing articles into the mechanism, wrapper feeding means, a pivoted stop, an element normally engaged by the stop and connected to the feeding means to initiate wrapper feeding operation of the same upon being released by the stop, a member so mounted that it is engaged and moved by an advancing article, and an adjustable connection between said member and the stop for actuation of the latter to release the feed initiating element in response to the movement of said member, the adjustment of said last named connection being effective to vary the time interval between the engagement of said member and the release of the element to initiate the wrapper feed.
